UNITED STATES PATENT OFFICE.

FRIEDERICH MÜLLER, OF HARTFORD, CONNECTICUT, ASSIGNEE TO PRATT & WHITNEY COMPANY, OF NEW YORK, N. Y., A CORPORATION OF NEW JERSEY.

RELIEVING MACHINE.

Application filed December 14, 1921. Serial No. 522,304.

To all whom it may concern:

Be it known that I, FRIEDERICH MÜLLER, a citizen of the United States, residing at Hartford, in the county of Hartford and 5 State of Connecticut, have invented certain new and useful Improvements in Relieving Machines, of which the following is a specification.

My invention relates to relieving machines and particularly to relieving machines for operating on cutter blanks having helical teeth.

One object of my invention is to provide a relieving machine that shall cut a blank, 10 having helical teeth provided either with radially arranged or non-radially arranged cutting faces, to a rectilinear or to a non-rectilinear contour while relieving the teeth along lines extending backwardly, inwardly and to the right or to the left, as desired, 15 and compensating such relieving operation at different blank diameters in case the cutting faces of the blank teeth are non-radially arranged.

Another object of my invention is to provide a relieving machine that shall form a blank, having helical teeth provided with either radially or non-radially arranged cutting faces, to the contour of a former member 20 while varying the length of the contour formed on the blank relative to the length of the contour of the former member to compensate for changes in length of the blank contour which are effected during the 25 hardening process.

Another object of my invention is to provide a relieving machine of the above indicated character that shall control a plurality of cutting tools to cut a plurality of cutter blanks in accordance with a former member, 30 having a predetermined contour, while effecting relieving movements of the tool in conformity with helical teeth on the blank and compensating such relieving operation 35 of the tools at different blank diameters in case the helical teeth of the blanks have non-radially arranged cutting faces.

Another object of my invention is to provide a relieving machine for shaping a cutter blank, having helically inclined teeth, 40 to any predetermined contour, that shall vary the rotative movement of the blank carrying spindle by means of a rack and pinion in accordance with the inclination 45 of the teeth of the blank and that shall pro-

vide means for resetting the rack in case a very long blank is being cut.

A further object of my invention is to provide a relieving machine for shaping a cutter blank to any predetermined contour 60 that shall be provided with a slide for withdrawing the tool from engagement with the blank at predetermined intervals, means including a cam bar for raising the slide upon each withdrawal to permit free movement 65 thereof, and means comprising oil cylinders and valves alined therewith for retarding the return movement of the tool.

More specifically my invention comprises a relieving machine for forming a blank, 70 which is provided either with helical or straight teeth having radially arranged or non-radially arranged cutting faces, to any predetermined contour. The machine is provided with mechanism for effecting relieving 75 movements of the tool along lines which extend backwardly, inwardly and to the right or left, as desired. The relieving movements are effected in accordance with the shape of the teeth on the blank and in 80 case the blank teeth are provided with non-radially arranged cutting faces compensation is effected for the relieving movements. The cutting tool is guided in accordance with the contour of a former member and 85 means is provided for so moving the former member during the operation of the machine as to vary the length of the contour cut on the blank relative to the length of the contour of the former member. The movement 90 of the former member serves to compensate for changes in length of the blank which may be effected during the hardening process.

The machine may also be provided with a tool post carrying a plurality of cutting tools whereby a plurality of tools may be simultaneously controlled by one former member. The cutting tools may operate simultaneously on one blank or may operate on a corresponding number of blanks. Each 100 cutting tool is provided with a rear face which is formed to the same angle as the relief on the front of the tool. By so constructing each cutting tool, it may be sharpened by grinding the top faces and may then 105 be reinserted in position without disturbing the relative position of the cutting tool to the blank.

The mechanism disclosed in this application includes some features of the machines 110

disclosed in my patents Nos. 1,429,617 and 1,443,638 respectively dated September 19, 1922 and January 30, 1923, and is adapted to cut a cutter such as is described and 5 claimed in my copending application Serial No. 524,586 filed December 24, 1921.

In the accompanying drawings:

Figure 1 is a front elevational view of a machine constructed in accordance with my 10 invention, certain parts being broken away and others being shown in section.

Fig. 2 is a plan view with certain parts shown in section. In this view the covers for the head stock and other gearing are 15 removed for the sake of clearness.

Fig. 3 is a vertical longitudinal sectional view of the machine.

Fig. 26 is an end elevational view, partially in section, of the mechanism shown in Fig. 24.

Fig. 27 is a diagrammatic view showing 75 the relation of the levers illustrated in Figs. 24, 25 and 26.

Fig. 28 is a diagrammatic view showing in development a cutter having teeth provided with non-radially arranged cutting 80 faces.

Figs. 29 and 30 are detail views of the adjusting bar.

Figs. 31 and 32 are detail views of the 85 correcting lever.

Figs. 33 and 34 are respectively plan and end elevational views of a modified tool post carrying a plurality of cutting tools.

Fig. 35 is a section along the line 35-35 of Fig. 33.

Fig. 36 is a section along the line 36-36 of Fig. 33.

Referring to the drawings, a relieving machine, which is adapted to practice my invention, is provided with a main frame 95 or bed 1 upon which the other parts of the machine are mounted. A headstock 2 and a tailstock 3 are provided for carrying the blank which is to be operated on. A tool holding-and-operating mechanism 4 100 is provided, as shown in Fig. 1. Preferably the headstock 2 and the tailstock 3 are so arranged as to hold the blank against longitudinal movement, the tool mechanism 4 being moved longitudinally along the blank 105 in the manner to be presently set forth. When the machine is so constructed, the headstock 2 is fixedly secured to the bed, preferably being formed in part integrally therewith, as shown. The tailstock 3 is adjustable along the bed to accommodate blanks or blank arbors of different lengths. 110

The headstock 2 is provided with a rotatable spindle 5 mounted in suitable bearings 6 and 7. Secured to the spindle 5, in any suitable manner, is a collet chuck 8 which may be of any usual or preferred form and which is adapted to grip either the shank of the tool to be formed and relieved or an arbor upon which the tool is 115 mounted. As illustrated, there is a blank A mounted upon an arbor B, the arbor being engaged by the chuck 8. A drive mechanism including a driving member in the form of a worm wheel 9, which meshes with a worm member 10 on a transverse rotatable shaft 11, is provided for rotating the spindle 5.

The tailstock 3 may be of any usual or preferred construction, and is adjustable 120

10 along ways 12 and 13. The tailstock 3 can be secured in adjusted position by means of a clamp 14 which is controlled by a lever 15. The tailstock spindle 16, which carries a center 17, can be moved longitudinally by means of a screw 18 under the control of a hand wheel 19. A handle 20 is provided for clamping the sleeve in adjusted position. As shown in Fig. 2, the center 17 is adjusted into engagement with the end of the arbor B.

15 The tool mechanism 4 includes a carriage 21 which is longitudinally movable along ways 22 and 23 on the bed 1. A slide 24, which is mounted for transverse movement with respect to the carriage 21, carries the cutting tool. In Figs. 2, 7 and 8 of the drawings I have shown a non-rotary lathe tool 25, and such a tool is preferable for 20 many classes of work. However, when preferred a rotary tool can be used.

25 As stated at the outset, a machine adapted to practice my invention is adapted for cutting a blank having a varying diameter. The diameter may vary uniformly from end to end of the blank, thus providing a uniform taper, or it may vary in any desired way so as to provide the blank with any predetermined contour differing from a 30 straight line. The variations in the diameter of the blank are determined by moving the slide 24 together with the tool transversely, and preferably, for regulating and controlling the transverse movements, I provide a former and a former pin, one carried in fixed position on the bed 1, and the other carried by the slide 24. As illustrated, a former member 26 is carried by the bed 1 and a former pin 27 is carried by the 35 slide 24. The former 26 has exactly the same contour with which the blank is to be formed and the former pin 27 has exactly the same shape as the cutting tool 25. The pin is detachably secured to the slide in a 40 manner to be hereinafter set forth, so that it can be removed and another pin be substituted corresponding to a tool differing in shape from the tool 25 which is shown. A bracket 28, which is rigidly secured to the bed 1, is provided for supporting the 45 former member 26. In order to permit adjustment, the former 26 is secured to a slide 29 which is longitudinally movable along a suitable guideway 30 on the bracket, a 50 screw 31 being provided for effecting longitudinal movement. The slide can be locked in adjusted position by means of screws 32, 32 which engage a gib member 33. The slide 29 is provided with a T-slot 55 34, which is adapted to receive T-bolts 35 passing through the former member. Such arrangement is provided to permit the ready adjustment of the former member. To further assist in holding the former 60 member in place and to prevent any possible

free movement thereof, a hooked bolt 36 is provided which, when tightened, serves to draw the former member back against a suitable shoulder on the slide. In practice, a former member 26 is selected having 70 the contour with which the blank A is to be formed and then by means of the slide 29 the former is adjusted longitudinally until it bears the same relation to the former pin 27 that the blank A bears to the tool 75 25. As the carriage 21 is moved longitudinally the slide 24 with the tool 25 is moved transversely so as to keep the former pin 27 in engagement with the former 26.

80 In order that the tool may be given a relieving movement along lines extending backwardly and inwardly to properly relieve the several teeth on the blank, it is not rigidly secured to the slide 24 but is transversely movable thereon. A slide 37, 85 which is transversely movable along a suitable guideway is mounted on the slide 24. A mechanism, for effecting regular reciprocating relieving movements of the slide 37 and the tool in suitable timed relation with the rotative movement of the blank, is carried in part by the slide 24. In order that the tool may be adjusted for blanks of different sizes, a tool-carrying slide 38 is provided which is transversely movable on 90 the slide 37. A screw 39, which is rotated by means of a hand wheel 40, is provided for moving the slide 38. The slide 38 is provided with a transverse guideway 41 and a tool post 42 is mounted on a slide 43 which 95 operates in the guideway 41. Preferably the tool post is formed as an integral part of the slide 43. The slide 43 not only serves to effect adjustment of the cutting tool but also serves to effect side relieving movements of the tool in a manner to be hereinafter set forth. The tool post has a tool-receiving aperture provided with a horizontal top wall 44 exactly at the level of the 100 axis of the blank. The tool 25 is positioned 105 with its top surface engaging the horizontal wall 44 of the tool post and is held in this position by means of a wedge 45. The rear end of the cutting tool 25 is formed 110 with an angle exactly corresponding to the relief angle on the front end of the tool. The rear end of the tool is engaged by a bolt 25^a which serves to adjust the cutting end of the tool relative to the blank A. When the bolt 25^a is adjusted, the tool may 115 be removed, ground on the top face for sharpening, and returned into exact position without changing the setting of the bolt 25^a.

120 It will be observed that, with the construction described, the tool is maintained in parallelism as it moves longitudinally for feeding or inward and outward to follow the contour.

125 The relieving mechanism for moving the 130

slide 37 together with the tool 25 includes a rotatable relieving cam 46 which is mounted on the slide 24 so as to be bodily movable therewith. As shown, the cam is mounted 5 on a longitudinal rotatable shaft 47 which is mounted in bearings 48 and 49 on a bracket 50 depending from the front of the slide 24. A lever 51 is pivoted between its ends on the slide 24 and at its lower end is provided with a roller engaging the cam 46. The upper end of the lever 51 engages an abutment 52 on the slide 37. A coil spring 53 is interposed between the slide 37 and the slide 24, this spring tending to press the slide 37 forward, thus holding the abutment 52 in firm contact with the upper end of the lever 51. It will be seen that, when the cam 46 is rotated, the lever 51 will be oscillated, thus giving a reciprocating movement 10 to the slide 37 and to the tool 25. The shape of the cam 46 is such that the slide 37 is moved forward relatively slowly at a uniform rate so that the tool may effect a relieving cut, and is then drawn back relatively 15 rapidly so as to withdraw the tool and position it for another cut.

The cam 46 is driven in timed relation with the blank rotation, as before stated. For rotating the cam, I make use of the 20 aforesaid transverse shaft 11. A shaft 54, which is mounted partly in the main frame 1 and partly in a bracket 55 secured thereto, is positioned immediately below the shaft 11. The two shafts 11 and 54 are connected 25 by means of a gear wheel 56 on the shaft 11, a gear wheel 57 on the shaft 54 and an idler gear wheel 58 meshing with the two gear wheels 56 and 57. The idler gear wheel is mounted on a bearing stud 59 which is carried 30 by an adjustable slotted arm 60. The arm 60 is carried by a hub 61 which assists in supporting the shaft 11. The speed ratio between the two shafts 11 and 54 can be changed by removing one or both of the 35 gear wheels 56 and 57 and substituting other gear wheels of different diameters, it being clear that the idler gear wheel 58 can be adjusted to mesh with such differently diametered gear wheels. A vertical shaft 62 is 40 mounted in the bracket 55 and is driven from the shaft 54 by means of bevel gearing 63. The shaft 62 serves to drive a longitudinal splined shaft 65 by means of bevel 45 gearing 64. The shaft is supported partly in a bearing 66 secured to the bed and partly in bearings 67 on a depending bracket 68 secured to the carriage 21.

A worm 69, which is mounted on the shaft 65 between the bearings 67, is splined to the 50 shaft. The worm 69 meshes with a worm wheel 70 which is connected with a transverse shaft 71. The worm wheel 70 and the shaft 71 are rotatably mounted in a bearing 72 formed in the bracket 68, and in a bearing 73 formed on a supplemental bracket 74

secured to the bracket 68. A bevel gear wheel 75 is slidably mounted on the shaft 71 and is engaged by a bearing 76 on the aforesaid bracket 50 depending from the front end of the slide 24. The bevel gear wheel 75 meshes with a bevel gear wheel 77 on the shaft 47. The bevel gear wheel 75 and the shaft 71 are splined or otherwise suitably constructed so that the bevel gear wheel is rotated, but is at the same time free to move 75 transversely of the machine when the slide 24 is moved. Inasmuch as the bevel gear wheels 75 and 77 are both supported by the bracket 50, they are at all times held in mesh. It will be seen that with this construction power is transmitted from the shaft 11, through the several parts that have been described, to the shaft 65, and is transmitted from the shaft 65 to the shaft 47 and the cam member 46, the connection between 80 the shaft 65 and the shaft 47 being such that free transverse movements of the cam member and associated parts is permitted. The cam member 46 is given one complete rotation for each tooth of the blank. The machine can be adjusted for blanks with different numbers of teeth by changing the gear wheels 56 and 57, as already explained.

As has already been stated, the machine is adapted for cutting blanks having helical teeth. In order that blanks with such teeth may be properly relieved, it is necessary to effect the relieving movements of the tool in peculiar relation to the rotative movement of the blank so that the relief may be in conformity with the helical teeth. I have stated that the relieving movements of the tool are effected in timed relation to the rotative movement of the blank; and, for any given position of the carriage, this timed relation is fixed and definite, but when the carriage is moved to bring the tool into a new cutting position, it is necessary to vary the relation between the relieving movements of the tool and the rotative movement 100 of the blank. For this purpose I make use of a mechanism which is in many respects similar to that set forth in my Patent No. 1,429,611 dated September 19, 1922. The present construction differs, however, in that 105 I have so arranged the mechanism that the aforesaid relationship is varied by changing the rotative movement of the blank rather than by changing the relieving movements of the tool. While I prefer to change the blank rotation, it will be understood that my present invention in its broader aspects 110 is not limited in this respect.

In the construction illustrated, the driving member or worm wheel 9 is not connected directly with the spindle 5 but is connected indirectly by means of suitable 125 gearing 78 which can be supplementally moved to change the spindle rotation. By preference, this gearing is bodily rotatable 130

and includes a rack and pinion, the rack being longitudinally slidable in accordance with the longitudinal movements of the carriage 21. A sleeve 79 is coaxially mounted with the spindle 5 and is supported by bearings 80 and 81 in the headstock. The inner end of the sleeve 79 preferably extends into and has a bearing in the outer end of the spindle 5. A frame 82 is recessed to receive the outer end of the spindle 5 and to engage the outer surface thereof. The aforesaid worm wheel 9 is rigidly secured to the sleeve 79. A shaft 83 having rack teeth formed thereon at 84 is slidably mounted in the sleeve 79. The shaft 83 is splined to the sleeve 79 so as to be rotatable therewith. A transverse shaft 85, which is provided with teeth 86 meshing with the rack teeth 84, is rotatably mounted in bearings in the frame 82. A transverse shaft 87 is also rotatably mounted in the frame 82. The two shafts 85 and 87 are connected by spur gear wheels 88 and 89. A third rotatable shaft 90 is rotatably mounted in the frame 82. A worm 91, which meshes with worm teeth 92 formed in the periphery of the spindle 5 near the end thereof, is secured to the shaft 90. A gearing is provided at the side of the bracket 82 opposite from the gears 88 and 89 for connecting the shafts 87 and 90. A gear wheel 93 is mounted on the shaft 87, and a gear wheel 94 is mounted on the shaft 90. An adjustable slotted bracket 95 is mounted on the frame 82 and this carries adjustable bearing studs 96 and 97 on which are mounted, respectively, idler gear wheels 98 and 99.

An annularly grooved collar 100 is carried by the shaft 83 near the outer end thereof. A longitudinal guide stud 101 is rigidly secured to the main frame 1 adjacent the shaft 83. A bracket 102 having a fork 103 entering the groove in the collar 100 is slidably mounted on the stud 101. The bracket 102 is apertured to receive a longitudinal rod 104, which is connected at its right-hand end with the carriage 21. The bracket 102 may be clamped to the rod 104 in any desired relative position and preferably by means of screws 105, 105 provided with handles 106.

It will be seen that, when the carriage 21 is moved longitudinally along the bed, the rod 104, together with the bracket 102, will be moved at the same time and to the same extent. By reason of the engagement of the fork 103 with the collar 100 the shaft 83 is similarly moved, thus moving the rack teeth 84. When the rack slides longitudinally the pinion 86 is turned and this serves, by means of the gearing and the several shafts that have been described, to turn the worm 91. The rotative movement of the worm 91 serves to turn the

spindle 5 relatively to the frame, 82 and the sleeve 79. It will be understood, as before stated, that the entire gearing 78 rotates bodily with the spindle 79. It will therefore be clear that the relative movement of the spindle 5 with respect to the sleeve 79 simply serves to either increase or decrease the spindle rotation to a certain extent. However, the relative movement of the spindle 5 is determined by the longitudinal movement of the rack 84, which in turn is determined by the longitudinal movement of the carriage 21 and of the cutting tool 25 carried thereby. Inasmuch as the relieving cam 46 reciprocates the tool 80 with a frequency which is normally uniform, and inasmuch as the spindle 5 and the blank are given a changed rotation which is in exact proportion to the longitudinal movement of the carriage and the tools, it is clear that the relieving movements are effected in such relation to the blank as to be in conformity with helical teeth.

In case a very long cutter is being formed in the machine, the rod 83 may be so moved to the left, as shown in Fig. 3 of the drawings, as to move the rack teeth 84 beyond the gear teeth 86. In order to permit the cutting of extremely long blanks, the gear wheel 88 is detachably connected to the shaft 85 which carries the gear teeth 86. The shaft 85 is preferably provided with a flange 85^a to which the gear wheel 88 is connected by means of a removable pin or bolt 88^a.

If the end of the rod 83 carrying the rack teeth 84 approaches the shaft 85 carrying the gear teeth 86 during the operation on a cutter blank, it is necessary to disconnect the gear wheel 88 from the shaft 85 for resetting the rod 83. The pin 88^a is removed for disconnecting the gear wheel 88 from the shaft 85 and the screws 105 operated by the handles 106 are loosened to release the clamp 102 from the rod 104. The rod 83 carrying the rack teeth 84 is moved forward or to the right as shown in Fig. 3 of the drawings until the opposite end of the rack teeth approach the shaft 85. The pin 88^a is inserted in position for connecting the gear wheel 88 to the shaft 85 and the clamp 102 is fastened to the rod 104. By such means, it is apparent the machine may be accommodated to operate on blanks of extremely long lengths.

The amount of variation of the spindle 5 and blank rotation can be changed in accordance with the degree of inclination of the helical teeth by removing one or the other or both of the gear wheels 93 and 94 and substituting other gear wheels of different diameters. The idler gear wheels 98 and 99 can be properly adjusted to mesh with such differently sized gear wheels. It is also possible to cause the rela-

5 tive movements of the spindle 5 to take place in either direction in conformity with helical teeth inclined in either direction. As illustrated, the machine is adjusted for cutting teeth with left-hand helices. For cutting teeth with right-hand helices the idler gear wheel 98 is removed and the gear wheel 99 is adjusted to mesh directly with the gear wheels 93 and 94. When it is desired to 10 cut a blank with straight teeth instead of helical teeth, the gearing is rendered ineffective, as for instance by loosening the clamping screws 105, thus permitting the rod 104 to slide freely through the bracket 15 102. By loosening the clamping screws 105 it is possible to preliminarily adjust the carriage without effecting the position of the spindle 5 and blank. When the cutter and the blank have been properly adjusted 20 relatively, the handles 106 are turned to connect the carriage with the mechanism for controlling the spindle rotation.

From the foregoing description it will be observed that in following helical teeth as 25 described, the blank is rotated in each instance through a little more or a little less than one revolution, as required for right-hand or left-hand helices. It will further be seen that during each rotative movement 30 of the spindle 5 and blank a whole number of relieving movements are effected.

The blank A, shown in Fig. 7, is provided with teeth having their front cutting faces arranged exactly radially. Frequently, however, it is desired to provide a cutter 35 with undercut or hooked teeth; that is, teeth having their front cutting faces inclined with respect to radial lines. Such a cutter is set forth in my patent for milling cutters, No. 1,443,641 dated January 30, 1923. For cutting a blank with undercut faces, it 40 is necessary to vary the ordinary relation between the relieving movements of the tool and the rotative movement of the blank as the cutting tool moves inward or outward 45 to conform to different blank diameters. When such blanks are to be cut, the mechanism heretofore described may be somewhat modified.

50 One way of varying the relation will be understood by reference to the diagrammatic Fig. 18. In this view t may be considered to be a fragmentary sectional view taken at the maximum radius r of a cutter C having undercut faces. Under the control of the former and the former pin, the cutting tool 25 is at a distance r from the blank axis and is in position to engage the point of the tooth shown and to cut the proper relief line $d-d$ thereon. The tooth section at a small radius r' is shown at t' . For this radius, without special provision being made, the tool 25 would be in the position indicated by dotted lines at the distance r' from the blank axis. However, by

reason of the inclined cutting face on the blank, the blank tooth would not be in engagement with the tool but would be separated therefrom by the angle m' . The tool, however, would immediately start its inward relieving movement notwithstanding the fact that the blank tooth had not yet reached it, and the result would be the cutting of an incorrect relief line $d'-d'$. For a still smaller radius r'' of the blank, as shown at t'' , the result would be similar except that the point of the tooth would be separated from the tool by a greater angle m'' , with the result that the incorrect relief line $d''-d''$ would be further from the correct relief line $d-d$.

In order to avoid the errors which would occur, as shown in Fig. 18, I vary the relationship between the relieving movements of the tool and the rotative movement of the blank in such a way that the tool, as concerns its relieving movements, is always in the same position when engaged by the front edge of the tooth. This will be clear from an inspection of Figs. 19 and 20. Fig. 19 shows the tool at the same radius r' from the blank axis as was shown in Fig. 18, but the relation of the relieving movement has been so changed that the blank is in position to be engaged by the point of the tool when the relieving movement starts. The tooth is therefore cut with the correct relief line $d-d$. Similarly, in Fig. 20, the tool is shown at the same distance r'' from the blank axis as was shown in Fig. 18, but the relation of the relieving movement has been so changed that the blank is in position to be engaged by the point of the tool when the effective relieving movement starts. The tooth is therefore cut with the correct relief line $d-d$. It will be seen that the operation, as illustrated in Figs. 18 to 20, is in no way effected by or dependent on the longitudinal inclination of the cutting faces. In other words, it is immaterial whether the cutting faces be helical or straight.

The required variations in the relationship between the relieving movements of the tool and the rotative movement of the blank can be brought about either by changing (usually advancing) the blank movement or by changing (usually retarding) the tool movements. I have found it simpler, to retard the tool movements, and this is particularly desirable when means are provided as herein disclosed for changing the blank movement to conform to helical teeth.

Referring to Figs. 2, 7 and 8 and particularly to Figs. 24, 25, 26, 27, 28, 29, 30, 31 and 32, the preferred manner of compensating the relieving operation at different blank diameters for the undercut teeth or non-radial cutting faces on the blank will be described. The former pin 27 is preferably

love-tailed to a sliding bar 107 and is firmly connected thereto by means of a bolt 108. The bar 107 is slidably mounted in an upstanding portion 109 extending from the slide 24 and an arm 110 which is attached to the portion 109. The arm 110 is shown attached to the extension 109 by means of bolts 111, but if so desired, such arm may be made an integral part of the slide 24. The bar 107, which slides in a slot formed in the extension 109 and the arm 110, is provided with shoulder portions 112 which are engaged by plates 113. The plates 113 are attached to the arm 110, in any suitable manner, as by means of screws 114 and hold the bar 107 in position.

A set screw 140 is provided for holding the screw 138 in any adjusted position. A pin 141, having a center point marked therein, is mounted in the lug 139 and together with the portion 137 of the lever 131 serve as reference points for adjusting the lever 121.

A second slot 142, which is preferably disposed perpendicularly to the slot 133, is formed in the lever 121. A correcting lever 143 is provided with an elongated portion 144 which is fitted to the slot 142. A pin 145, which is attached to the bar 107, extends through the portion 144 of the lever 143 and is provided with a center point marked therein to serve as a reference point when adjusting the screw 123. The lever 143 is connected by a pin 146 to a block 147 which slides in a slot formed in the arm 110.

In the mechanism disclosed in Figs. 24, 25, 26, 29, 30, 31 and 32, the center marks on the pin 145 and the connecting lever 131 are adjusted by the screw 123, a distance apart which is equal to the maximum radius of the blank. The pin 145 and the correction lever 143, which are mounted upon the slide 24, effect no translatory movement during such operation. The connecting lever 131, which carries the guide lever 121, is moved relatively to the slide 24. The center marks on the pin 141 and on the connecting lever 131 are moved a distance apart by the screw 138 in accordance with the undercut on the teeth of the blank and the angle of relief for the teeth. When adjusting the relative position of the pin 141 and the connecting lever 131, it should be noted that the lever 131 is held against transverse movement by the arm 120 which is supported on the carriage 21.

Consequently, the guide lever 121 is given a movement of rotation. Thus, the slot 142 is placed at an angle to the center line of the bar 107 and such angle is varied in accordance with the undercut and the angle of relief. Preferably the screw member 138 is adjusted prior to the adjusting of the screw 123.

The elongated portion 144 of the correction lever 143, which is fitted to the slot 142 in the guide lever 121, compels the correction lever 143 to move an angular distance in accordance with the angular movement of the guide lever. Consequently, when the slot 142 is angularly moved with reference to the center line of the bar 107,

A bracket 118 is mounted on one of the projecting portions 117 of the carriage 21 and is connected thereto by bolts 119. The bracket 118 carries a supporting arm 120 which in turn pivotally supports an L-shaped guide lever or member 121. The supporting arm 120 is provided with a block portion 122 which slides in a suitable guideway formed in the bracket 118. A screw 123, which is attached to the block portion 122, is provided for adjusting the position of the bar 107 and the former pin 27 in accordance with the maximum diameter of the blank for a purpose to be hereinafter set forth. A gib member 124, which is held in position by set screws 125, is provided for holding the arm 120 in any set position. The screw 123 is rotatably mounted in a plate 126 which is attached to the bracket 118 by means of screws 127. A collar 128, which is an integral part of the screw 123, is disposed on one side of the plate 126 and a removable collar 129 is attached to the screw 123 by a pin 130 on the opposite side of the plate 126.

The arm 120 is attached to the guide member 121 by means of a connecting lever 131. The lever 131 is provided with an elongated portion 132 which fits within a slot 133 formed in the guide member 121. Shoulder portions 134 are provided which fit within grooves formed in the sides of the slot 133. A cylindrical portion 135 of the lever 131 is fitted to an opening in the arm 120 and a nut 136 is provided for holding the arm 120 and the lever 131 together. A portion 137, having a center point marked thereon, extends through the nut 136 to serve as a reference point when setting the former pin 27 for different blanks provided with different undercut.

A screw 138, which is threadedly con-

the correction lever 143 effects an angular movement, and, in so doing not only moves the block 147 in the slot formed in the arm 110 but also moves the bar 107 and the former pin 21 forward a small amount. It should be noted that, when the guide lever 121 is given a movement of rotation, the only point on the center line of the slot 142, which coincides with the center line of the bar 107, is the center of the pin 145. Consequently, when the slide 24 is moved forward to cut smaller diameters on the blank, the correction lever 143 is moved forward to increase the angular position of the slot 142 relative to the center line of the bar 107. The arm 120, which supports the guide lever 121, is, as before stated, mounted on the carriage 21 and consequently prevents the guide lever 121 from effecting any movement of translation during the forward movement of the slide 24. Thus, the forward movement of the correction lever 143 in the slide 142 compels the guide lever 121 to effect a movement of rotation about the part 135 of the connecting lever 131. The correction lever 143 is compelled to effect an angular movement in accordance with the angular movement of the guide lever. Such angular movement of the correction lever 143 effects a small translatory movement of the bar 107 and the former pin 27 relative to the slide 24.

In the above manner, the distance between the tool and the former pin is varied to compensate at different blank diameters for the non-radial cutting faces on the teeth. The means for determining the distance apart to set the center marks on the pin 141 and the connecting lever 131 will be disclosed more fully when reference is made to Figs. 27 and 28 of the drawings.

The adjusting mechanism disclosed in Figs. 24, 25, 26, 27, 28, 29, 30, 31 and 32 for varying the relation between the cutting tool and the former pin is set in accordance with the maximum diameter of the cutter blank, the amount of relief and the amount of undercut on the teeth of the blank. The screw 123 is adjusted to make the distance between the center marks on the pin 145 and the connecting lever 131 equal to the maximum radius of the cutter blank. The distance between the center marks on the pins 145 and 146 is made equal to one unit of length, preferably one inch. The distance between the center marks on the pin 141 and connecting lever 131 is obtained mathematically by a formula to be explained in describing Figs. 27 and 28. The distance between the center marks on the pin 141 and the connecting lever 131, when the slot 142 is parallel to the bar 107, is varied a distance to compensate the relieving operation at different

blank diameters in accordance with the undercut or the non-radial cutting faces on the teeth of the blank. 65

Referring to Figs. 27 and 28, it is assumed:

x =The change in distance between the former pin and the cutting tool. 70

e =Length of the correction lever 143 (one unit of length). 75

F'' =The correction factor for setting the compensating mechanism (Fig. 27). 75

y =Required change in position of relieving movement. 80

r =Radius of the cutter blank at any point. 85

F =Total relief including all teeth. 80

F' =The total undercut. 85

r^o =The maximum radius of cutter blank. 90

Referring to Fig. 28, the distance y that it is necessary to change the position of the relieving movement for non-radially arranged cutting faces is mathematically determined as follows: In Fig. 28 it is assumed k is the center of the cutter blank, the line zk is the cutting face of a tooth if the cutting faces were radially arranged, and the line zh is the cutting face of a tooth if the cutting faces were non-radially arranged. The undercut is assumed to equal F' and accordingly the line zh is drawn tangent to the circle having a radius equal to F' . The line gh is drawn parallel to, and at a distance F' , from the line zk . 95

At any point on the cutter having a radius r which is less than the maximum radius r^o , the angles pkq and qkl are constructed with the lines pk and qk equal to the radius r . Comparing a cutter blank having radially arranged cutting faces with a cutter blank having undercut cutting faces, it is apparent that in the case of undercut teeth, the cutting tool would approach too near the center k of the cutter blank before the cutting faces were reached by reason of the relieving movement. Thus, for a radius r , the cutting tool would approach the center k of the cutter by a distance equal to relief effected through the angle lkq . Inasmuch as the total relief is F , the relieving distance for which compensating must be effected is equal to 100

$$\frac{(\text{angle } qkl)}{360} F = y.$$

In other words, the position of the relieving movement must be changed or retarded a distance $\frac{(\text{angle } qke)}{360} F$ when cutting a point on the cutter blank having a radius r . 110

Referring to Fig. 28.

The angle qkl =angle pkl —angle pkq . 125

The angle pkq =angle gkz .

It is apparent that the angle pkq equals the angle gkz when the straight line zq is

assumed to be turned through an angle pkg about the center k . Upon being turned through such an angle the line zq takes a position coinciding with the line gp . In like manner the line zl assumes a position coinciding with the line gp when rotated through an angle gkz about the center k . Therefore angle qkl = angle pkl - angle gkz and

$$10 \quad y = \frac{(\text{angle } pkl - \text{angle } pkg)}{360} F = \frac{(\text{angle } pkl - \text{angle } gkz)}{360} F$$

$$15 \quad \text{Sine of angle } pkl = \frac{F'}{pk} = \frac{F'}{r}$$

$$\text{Sine of angle } gkz = \frac{F'}{gk} = \frac{F'}{r^o}$$

20 Inasmuch as the value of y , the relieving distance for which compensation must be effected, is given in terms of the angle, values must be obtained for angles pkl and gkz .

25 The angle pkl is equal to the arc which corresponds to the known sine of such angle.

Angle $pkl = \arcsin \frac{F'}{r}$. The angle gkz is 30 equal to the arc which corresponds to the sine $\frac{F'}{r^o}$. Angle $gkz = \arcsin \frac{F'}{r^o}$.

Therefore

$$35 \quad y = \frac{(\text{angle } pkl - \text{angle } gkz)}{360} F = \frac{F}{2\pi} \left(\arcsin \frac{F'}{r} - \arcsin \frac{F'}{r^o} \right).$$

40 The above value of y is the amount the tool must be retarded at any radius r of the cutter blank, when compared with the position of the tool at a radius r^o . The retarding amount when compared with a 45 position beyond r^o is larger, and the retarding amount is largest when the position compared with is considered to extend to infinity. If we consider r^o to equal infinity, then $\arcsin$

$$50 \quad \frac{F'}{r^o} = \frac{F'}{\infty} = 0.$$

Therefore, if we consider r^o to equal infinity the retarding amount

$$55 \quad y \text{ equals } \frac{F}{2\pi} \left(\arcsin \frac{F'}{r} \right).$$

60 In the case of very small angles, such as are being considered, the $\arcsin$ may be taken equal to sine. The solving of the above equation by substituting the sine for the $\arcsin$ does not produce an exact mathematical result but an approximation is obtained which is very much closer to the 65 correct result than can be worked to by

modern tools. Accordingly we may use an approximation formula

$$y = \left(\frac{FF'}{2\pi} \right) \frac{1}{r}$$

70 for determining the required correction.

It is apparent from the above discussion that the tool must be retarded or compensated an amount which is inversely proportional to the varying radius r of the 75 cutter blank. In other words the relieving movement must be retarded an amount which varies inversely with the radius of the cutter blank. Referring to Fig. 27, it is shown that the compensating mechanism disclosed in Figs. 24 to 32, inclusive, satisfies the above requirement and changes the position of the relieving movement inversely in accordance with the radius of 80 the cutter blank.

85 The levers, which are shown in Figs. 24 to 32, inclusive, are diagrammatically illustrated in Fig. 27 in order to more clearly set forth their operative relation to each other. The line af' in Fig. 27 is equal to the radius r of the cutter blank at any point and is the distance between the center marks on the pin 145 and connecting lever 131. The line af is equal in length to e and is placed in the position assumed by the correction lever 143 for any desired compensation of the relieving operation. The lines ab and fb are respectively drawn perpendicularly and parallelly to the line af' . The line fb equals the distance x , which represents the variation in distance between the cutting tool and the former pin that must be made for certain values of the relief, the undercut and the diameter of the cutter blank. The line $b'f'$ is drawn perpendicularly to the line ab' and has a length F'' which is to be determined. The line ab' is drawn in the angular position necessary to place the slot 142 when a correction x is made in the distance between the cutting tool and the former pin. Inasmuch as the triangles abf and $af'b'$ are right-angle 90 triangles, it is apparent

$$\frac{x}{e} = \frac{F''}{r} \text{ and } x = \frac{ef''}{r}.$$

95 The value of x thus obtained varies inversely in accordance with the radius r of the cutter blank. By taking x equal to y , a value for the correcting constant F'' can be obtained for setting the compensating mechanism.

$$100 \quad y = \left(\frac{FF'}{2\pi} \right) \frac{1}{r} \text{ and } x = \frac{ef''}{r}$$

115 Therefore,

$$\left(\frac{FF'}{2\pi} \right) \frac{1}{r} = \frac{ef''}{r} \text{ and } F'' = \frac{FF'}{e2\pi}$$

120 The above formula although not absolutely mathematically correct will determine the 130

correction factor F'' much closer than can be worked to on modern machines.

By means of the equation

$$F'' = \frac{FF'}{e2\pi}$$

the correction factor F'' may be determined inasmuch as e is a constant and the relief F and the undercut F' are known. Upon determination the value of F'' for a given cutter blank, the screw 138 is operated to adjust the distance between the center-punch marks on the pin 144 and the connecting lever 131 in accordance therewith. The normal distance between the two center-punch marks is diminished in accordance with the value of F'' . After setting the screw 138, the screw 123 is adjusted in accordance with the maximum radius of the cutter. The screw 123 is so adjusted that the distance between the center-punch marks on the pin 145 and on the connection lever 131 is equal to the maximum radius of the cutter blank. The cutting tool is finally set to cut the maximum radius on the cutter blank. Upon movement of the tool to cut a different radius, the position of the relieving movement is varied inversely with the value of r .

When the compensating mechanism is set for the maximum radius of the cutter a value of ω is indicated on the compensating mechanism inasmuch as the correction is referred to an infinite radius as above set forth. The value of ω thus indicated is

$$\left(\frac{FF'}{2\pi}\right) \frac{1}{r^0}$$

and is taken care of by adjusting the tool in engagement with the blank. The correction at any radius r when compared with an infinite radius is

$$\left(\frac{FF'}{2\pi}\right) \frac{1}{r}$$

The difference in the correction between points at radius r^0 and radius r or the correction at r when compared with the radius r^0 is

$$\frac{F}{2\pi} \left(\frac{F}{r} - \frac{F}{r^0} \right)$$

It will be seen that two independent variations are effected in the relation between the relieving movements of the tool and the rotative movement of the blank. One of these variations is dependent upon the longitudinal movements of the tool along the blank and the other of the variations is dependent upon the inward or outward movement of the tool whereby the blank is cut with different diameters. In the preferred embodiment of the invention, as shown and described, the first said variation is effected by changing the rotative movement of the blank and the second variation is effected by changing the relieving movements of the

tool. It will be understood, however, that the invention is not limited to this exact construction, as any mechanism for effecting the required variations in the relationship would be within the scope of the invention.

A screw 150, which engages a nut 151 carried by a bracket 152 depending from the carriage, is provided for moving the carriage 21 longitudinally along the bed 1. The screw 150 is supported at its left-hand end in a bearing 153 formed in a bracket 154 secured to the bed. A transverse shaft 155, which is connected with the screw 150 by means of bevel gearing 156, is mounted in the bracket 154. At the front end of the shaft 155 is a hand wheel 157 by means of which the screw 150 may be turned manually to move the carriage 21. In order that the carriage may be moved automatically to feed the tool from one cutting position to another, a suitable mechanism is provided. This mechanism is preferably adapted to feed the carriage intermittently, but it will be understood that as concerns certain phases of the invention I do not so limit myself inasmuch as the carriage may be moved continuously if desired. Mounted in the bracket 154 is a transverse bearing pin 158 upon which is rotatably mounted a sleeve 159. A gear wheel 160, which meshes with a gear 161 on the shaft 155, is loosely mounted on the sleeve 159 near the inner end thereof. A ratchet wheel 162 is connected to the gear wheel 160. Gear teeth 163, which mesh with a gear wheel 164 secured to the shaft 150, are formed on the sleeve 159 near the outer end thereof. A ratchet wheel 165, which is similar to the ratchet wheel 162, is keyed to the sleeve 159. A swinging arm 166 is loosely mounted on the hub of the ratchet wheel 165. A link 167, which is adjustably connected at its left-hand end with an oscillating crank arm 168, is pivotally connected with the arm 166 near the lower end thereof.

The crank arm 168 is secured to a transverse rock shaft 169 which is mounted in a bearing 170 and which carries at its rear end a lever 171. A roller 172, which is positioned to be engaged by a cam member 173 on a longitudinal rotatable shaft 174, is carried by the lever 171 near the upper end thereof. A transverse pin 175, which carries two similar pawls 176 and 177 adapted respectively to engage the ratchet wheels 162 and 165, is mounted on the swinging arm 166. Either pawl can be thrown into or out of engagement with the corresponding wheel. The shaft 174 is rotated, in the manner to be presently described, and it will be seen that at each rotation thereof the arm 171 and the crank arm 168 are oscillated. The oscillation of the crank arm 168 is transmitted by means of the link 167 to the plate 166, the extent of oscillation of

the plate being adjustable by changing the shaft 11 can be driven from the shaft 178 at any one of a series of speeds. A short longitudinal shaft 192 is mounted in alignment with the main power shaft 178. The shaft 192 carries a clutch element which is adapted to be engaged by the aforesaid splined clutch element 181 on the shaft 178. When the clutch element is in its right-hand position as viewed in Fig. 4, it drives the gear wheel 180 and the several parts connected therewith. When the clutch element is in its left-hand position it drives the shaft 192. A transverse shaft 193 is suitably mounted in bearings in the bed and is connected with the shaft 192 by means of bevel gearing 194. The shaft 193 carries a worm 195 which meshes with a worm wheel 196 on the aforesaid longitudinal shaft 174.

5 162 or 165 is turned through a small angle, thus turning the shaft 155 and the lead screw 150 and moving the carriage 21. It will be seen that the carriage movement is relatively great when the pawl 176 is 10 in use, and is relatively small when the pawl 177 is in use. The desired amount of carriage movement may be obtained by selecting the proper pawl and by adjusting the crank arm connection.

15 Preferably the rotation of the spindle and of the blank is stopped during the feeding movement of the tool. I therefore provide two alternately acting mechanisms, one serving to rotate the spindle and the blank 20 through one revolution, or approximately one revolution, and also serving to effect the relieving movements of the tool, and the other mechanism serving to effect the longitudinal feeding of the tool and preferably 25 also serving to effect other movements to be described.

The mechanism for rotating the spindle and the blank has already been described in part, this mechanism including the transverse shaft 11, the worm 10 and the worm wheel 9. The machine is provided with a main power shaft 178, which is adapted to be driven in any suitable way, as for instance, by means of a belt on a pulley 179. 30 A gear wheel 180 is rotatably mounted on the shaft 178. The gear wheel 180 is preferably connected to the shaft 178 by means of a splined clutch element 181. The gear wheel 180 meshes with a gear wheel 182 on a longitudinal shaft 183. A long gear wheel 184 is secured to the shaft 183. The gear wheel 184 is surrounded by a sleeve 185 which is open at the forward upper side. A bushing 186 is slidably and rotatably mounted on the sleeve 185. The bushing 186 is provided with ears between which a gear wheel 187 is rotatably mounted. The gear wheel 187 meshes with the aforesaid gear wheel 184 on the shaft 183. A third longitudinal shaft 188 is provided, which carries a series of differently diametered gear wheels 189. The shaft 188 is connected with the aforesaid shaft 11 by means of bevel gearing 190. The bushing 186 can be moved 45 angularly and longitudinally on the bushing 185 so as to bring the gear wheel 187 into mesh with any one of the differently diametered gear wheels 189. A spring-pressed plunger 191, which is carried by the sleeve 186, is adapted to enter any one of a series of apertures in the sleeve 185 so as to hold the gear wheel 187 in proper position to mesh with any desired one of the gear wheels 189. It will be seen that by this 50 construction the shaft 188 together with the

A short longitudinal shaft 192 is mounted in alignment with the main power shaft 178. The shaft 192 carries a clutch element which is adapted to be engaged by the aforesaid splined clutch element 181 on the shaft 178. When the clutch element is in its right-hand position as viewed in Fig. 4, it drives the gear wheel 180 and the several parts connected therewith. When the clutch element is in its left-hand position it drives the shaft 192. A transverse shaft 193 is suitably mounted in bearings in the bed and is connected with the shaft 192 by means of bevel gearing 194. The shaft 193 carries a worm 195 which meshes with a worm wheel 196 on the aforesaid longitudinal shaft 174.

In the operation of the machine, it is desirable for the sleeve 79 and for the shaft 174 to each make one complete revolution alternately in succession. In order that the desired alternate movements of the sleeve and shaft may take place, I provide automatic mechanism for shifting the clutch element 181. The mechanism used is similar in principle to that shown and described in my Patent No. 1,273,903 for driving mechanism, dated July 30th, 1918. The clutch element 181 is provided with an annular groove into which fit rollers or projections on a forked lever 197. The lever 197 is transversely pivoted on the frame and is provided with a roller 198 by means of which it may be moved. A transverse rock shaft 199 is mounted in the frame above the forked lever 197. The rock shaft 199 carries at its rear end an arm 200 in which is mounted a spring-pressed plunger 201. As shown the plunger 201 is V-shaped at its lower end and is adapted to engage the roller 198. A lever 202 having upper and lower arms is secured to the rock shaft 199 at the front end thereof. The upper arm carries a roller 203 which is adapted to be engaged by a cam plate 204 secured to a cam drum 205 mounted on the sleeve 79. The lower arm of the lever 202 carries a roller 206 which is adapted to be engaged by a cam plate 207. The cam plate 207 is secured to a cam drum 208 which is mounted on the shaft 174. When the parts are in the positions shown in Figs. 3, 4 and 6, the sleeve 79 is in motion and continues to turn until the cam plate 204 engages the roller 203 and turns the lever 202 in a clockwise direction, as viewed in Fig. 2, or in a counter-clockwise direction, as viewed in Fig. 4. Such movement forces the spring-pressed plunger 201 over the top of the roller 198 and thus tends to swing the lever 197 in the direction to shift the clutch element into position to drive the shaft 192. When the shaft 192 is thus driven, the shaft 174 with the cam drum 208 thereon is driven in the direction indicated by the arrow in

Fig. 6. Such movement continues until the cam plate 207 engages the roller 206 and swings the lever 202 in a counter-clockwise direction, as viewed in Fig. 3, or in a clockwise direction, as viewed in Fig. 4. In other words, the cam plate 207 serves to restore the lever to the position which is shown in the drawings. The spring-pressed plunger 201 is again moved over the top of the roller 198 and tends to move the lever 197 in the direction to move the clutch element 181 into position to drive the gear wheel 180.

Preferably, I do not depend solely upon the shifting of the lever 202 for the timing of the movements of the clutch element 181. As illustrated, the lever 197 is provided with opposite fingers 209 and 210 which are adapted to be engaged respectively by latch members 211 and 212. The latch members are held in engagement with the fingers 209 and 210 by means of a spring member 213. Referring to Fig. 4, it will be seen that the latch 211 serves to prevent the movement of the lever 197 toward the left even after the arm 200 has been moved to its right-hand position. Similarly, the latch 212 serves to prevent the movement of the lever 197 toward the right even after the arm 200 has been moved to its left-hand position. A vertically slidable rod 214, which is normally pressed upward by a spring 215, is provided for releasing the latch 211. The upper end of the rod 214 is engaged by an arm 216 on a short transverse rock shaft 217. The rock shaft 217 carries a lever 218 at its front end. A roller, which is adapted to be engaged by a cam projection 219 secured to the worm wheel 9, is mounted on the lever 218. The cam projection 219 is so positioned with respect to the cam plate 204 that the plate first engages the roller 203 and moves the arm 200 into position to shift the lever 197. Subsequently, when the spindle 79 has completed the desired revolution, the cam projection 219 engages the roller on the lever 218, thus turning the rock shaft and the lever 216 and moving the rod 214 to release the latch member 211. The latch member having been released, the lever 197 turns under the action of the spring-pressed plunger 201 and disengages the clutch element from the gear wheel 180 and engages it with the shaft 192. The latch member 212 is mounted on a short transverse rock shaft 220 which carries a lever 221 at its front end. A roller is positioned at the upper end of the lever 221 to be engaged by a cam projection 222 on the cam drum 208. The cam projection 222 is so positioned with respect to the main cam plate 207 that the plate first engages the roller 206 and moves the arm 201 into position to shift the lever 197. Subsequently, when the shaft 174 has completed the desired revolution, the cam projection 222 engages to release the latch

212. The latch 212 having been released, the lever 197 turns under the action of the spring-pressed plunger 201 and disengages the clutch element from the shaft 192 and engages it with the gear wheel 180. It will be seen that by means of the mechanism described the spindle 79 serves to stop itself after making a complete revolution and to start the shaft 174. Similarly the shaft 174, after making one complete revolution, serves to stop itself and start the spindle 79. Thus these two parts operate alternately in continuous succession.

It is desirable to feed the tool longitudinally while out of engagement with the blank, that is, when the tool is opposite the groove between two teeth of the blank. The blank is therefore preferably mounted in the spindle so that at the position of stopping, the tool will be opposite a groove. The grooves are helical but the spindle and the blank are supplementally turned at each longitudinal movement this supplemental turning exactly compensating for the inclination of the grooves and insuring the stopping of the blank with a groove opposite the tool.

Preferably the tool is withdrawn at the time of each longitudinal movement, the former pin also being withdrawn from engagement with the former. This withdrawal is effected by mechanism operated by the shaft 174, the withdrawal being thus properly timed with respect to the feeding movement. An abutment 223 is associated with the slide 24. The abutment 223 is engaged by the upper end of a lever 224 which is longitudinally pivoted to the carriage 21. The lower end of the lever 224 is provided with a roller which is adapted to be engaged by a cam plate 225 on a cam disk 226. The cam disk 226 is secured to the shaft 174. At the beginning of the rotation of the shaft 174 the cam plate 225 engages the roller on the lever 224 and swings it in the counter-clockwise direction, thus moving the abutment 223 together with the slide 24 toward the front. In this way the tool 25 is withdrawn from the blank and the former pin 27 is withdrawn from the former 26. As the shaft 174 continues to rotate, the cam member 173 operates the feeding mechanism in the way already described, and the carriage 21 is moved longitudinally along the bed. After such operation the cam plate 225 permits the lever 224 to return to the position shown, and the slide 24 is permitted to move rearward carrying the tool 25 and the former pin 27 to their operative positions. It will be seen that by thus withdrawing the former pin from the former at the time of longitudinal movement, I avoid any difficulties incident to forcing the former pin along the former while in contact therewith. If the former pin were maintained in con-

tact with the former at all times difficulty would be experienced in effecting the longitudinal movement, particularly at places where the contour of the former is sharply inclined.

Preferably the former pin is restored to engagement with the former by a relatively slow movement with a minimum of pressure, so that there will be no tendency to bend or distort the pin or to secure uneven contact between the pin and the former. For this purpose I provide a mechanism for returning the carriage which is entirely independent in its operation from the mechanism for withdrawing it. The before mentioned abutment 223 is not connected directly to the slide 24 but is connected to a second slide 227 which is transversely movable independently of the first slide 24. Spring members 228 are interposed between the slide 227 and the carriage 21 and such spring members tend to move the slide 227 rearwardly, thus holding the abutment 223 at all times in engagement with the lever 224.

The two slides 24 and 227 are ordinarily connected by a lock. As shown most clearly in Figs. 3, 8 and 9, the lock includes a plate 229 located in the recess in the top of the slide 24. The plate 229 is provided with a boss which projects downward through a slot in the slide, and threaded into this boss is a vertical stud 230. The stud 230 extends through and closely fits an aperture in the slide 227. Two small bell-crank levers 231 are pivoted to the slide 227. The levers 231 are provided with horizontal upper arms which engage a collar on the stud 230. The lower ends of the levers are adapted to be engaged by a tapered cam bushing 232 which is vertically movable on the stud 230. When the bushing 232 is in its lower position, as shown, the levers 231 are forced outward, thus drawing the stud 230 downward and forcing the plate 229 into clamping engagement with the slide 24. In this way the slide 24 is firmly connected with the slide 227. When the bushing 232 is in its raised position, the levers 231 swing inward, thus permitting the stud 230 to move upward and release the plate 229 from its clamping engagement with the slide 24. A forked lever 233 having projections engaging slides or notches in the bushing, is provided for moving the bushing 232. Such lever is secured to a longitudinal rock shaft 234, which is mounted in bearings in the carriage 21. A lever 235 is connected with the lever 233. The lever 235 is provided with a roller which is adapted to be engaged by cam plates 236 and 237. The cam plates 236 and 237 are secured to a cam disk 238 which is mounted on the shaft 174. It will be seen that as the shaft 174 rotates, the cam plate 236 engages the roller on the lever 235, thus moving the lever 233 and the cam bushing 232 upward

and releasing the lock. Subsequently the roller is engaged by the cam plate 237, thus moving the cam bushing 232 downward and re-engaging the lock.

I have already stated that a supplemental mechanism is provided for returning the slide after it has been withdrawn in the way before described. Preferably, in order that this supplemental returning mechanism may operate without being effected in any way by the return movement of the slide 227, and in order further that the slide 24 may be returned with a minimum of effort, I provide a supplemental means for supporting the slide 24 after it has been unlocked from the slide 227. As illustrated, the carriage 21 is provided near its front and rear with sets of transverse pivot pins 239 and 240 which are mounted in brackets 239^a and 240^a. The brackets 239^a and 240^a are suitably mounted on the carriage. Arms 241 and 242 are supported by the pins 239 and 240. The arms are respectively provided with rollers 243 and 244 which are adapted to engage the bottom of the slide 24. The arms 241 and 242 are respectively provided with cam projecting portions which are adapted to be engaged by cam surfaces on cam bars 245. Thus, when the cam bars 245 are shifted rearwardly, the cam surfaces on them engage the cam projecting portions on the arms 241 and 242 and raise such arms for separating the slide 24 from the slide 227. The cam bars 245 are connected by a transverse yoke member 246. The yoke member is provided with slots or notches in which fit pivot bosses 247 projecting upwardly from the lever 233. The result is that when the lever 233 is swung upwardly to release the lock, the cam bar is shifted backwardly and the arms 241 and 242 are raised to lift the slide 24 off the slide 227 and support it independently. The action of the cam bar on the arms 241 and 242 is such as to effect a raising movement of the slide 24 without effecting any movement of translation of such slide. The actual raising of the slide 24 may be but a few thousandths of an inch. Coil spring members 248 are provided for returning the slide 24 rearward as soon as it has been released by the lock and elevated by the rollers. Preferably such spring members are located in long transverse cylindrical apertures 249 in the slide 24. The spring members abut at their rear ends against plugs 250 threaded into the apertures, and at their front ends abut against heads 251 on transverse rods 252. The rods 252 extend through central openings in the plugs 250 and are connected at their rear ends with brackets 253 which are mounted on the carriage 21. Preferably, the heads 251 are in the form of pistons and the forward parts of the apertures 249 constitute cylinders 254

in which the pistons 251 fit and move. A casting 255 is secured to the slide 24. The casting 255 is provided with a fluid reservoir 256 which communicates at its ends with the cylinders 254.

- The ends of the rods 252 adjacent to the pistons are each threadably connected to tubes 257 which are fitted to the cylinders 254. Preferably packing 257* is disposed between the tubes 257 and the pistons 251 to prevent the leakage of any oil contained in the cylinders 254 to the chamber containing the springs 248. A cap 258 having a second cap 259 connected thereto is threadably joined to the end of each tube 257. Preferably, packing is provided between the cap 258 and the tube 257 as shown in Fig. 17 of the drawings to prevent any leakage of oil contained in the tube 257. The end of the cylinder 254 is closed by a plug 260. The plug 260 has a passageway 261 formed therethrough which connects with the reservoir 256. A tube 262 is threadably connected to the inner end of the plug 260 and connects the passageway 261 to the cylinder 254. The tube is fitted to openings through the caps 259 and 258 and has a valve seat member 263 threadably connected to the end thereof. A valve plug 264, which is connected to a valve stem 265, is fitted to a valve seat in the member 263. A passageway is formed through the member 263 as shown in Fig. 17 of the drawings for connecting the tube 262 with the cylinder 254. Such opening is controlled by the valve plug 264. The valve stem 265 extends into the tube 262 and carries a collar member 266 which is pinned to it. A spring member 267 is located on the valve stem 265 between the collar member 266 and the end of the member 263 for exerting a force tending to seat the valve plug 264. A cap member 268 is secured to the outer end of the plug 260 and a rod 269 for adjusting the valve stem 265 is threadably connected to the cap 268. Suitable packing is provided between the rod 269, the cap 268 and the plug 260 for preventing the leakage of oil from the passageway 261. Near the inner end of the adjusting rod 269 an enlarged portion 270 is provided which is fitted to the tube 262. The enlarged portion 270 is provided with grooves for permitting the free passage of oil through the tube 262. The inner end of the rod 269 engages the end of the valve stem 265 and limits the movement of the valve plug. The rod 269 may be adjusted to change the limit of the closing of the valve as desired. The cylinders 254 together with a part of the reservoir 256 are filled with a suitable fluid, which is preferably a liquid such as oil. It will be seen that as soon as the slide 24 has been elevated and released from the slide 227, the spring members 248 tend to

move it rearward. This tendency, however, is resisted by the engagement of the pistons 251 with the liquid in the cylinders. This engagement forces the liquid out of the cylinders through the valve formed in the member 263, the tube 262 and into the reservoir 256. The liquid can pass through the valve in the member 263 only relatively slowly, and thus the return movement of the slide is made to take place very slowly. When the slide is moved quickly forward at the time of next feeding, the valve plug 264 moves to permit the liquid to flow from the reservoir back to the cylinders 254. The slow return movement causes the former pin to engage the former gently and with a minimum force, so that there is little or no tendency to bend or deflect the parts.

It will be noted that the several cam members 173, 225, 236 and 237 are so positioned in relation to each other that the operations which they respectively control take place in the following order: First, the two slides 227 and 24 are moved backward in unison, they being still locked together. Then the slide 24 is unlocked from the slide 227 and is at the same time elevated on the rollers 243 and 244. At or about the same time the carriage is moved longitudinally to feed the tool to a new cutting position. Then the slide 227 is permitted to return to its normal position. In the meantime the slide 24 is being moved slowly rearward under the control of the spring members 248 and the fluid regulating mechanism. After the completion of the return movement of the slide 24, the rollers 243 and 244 are lowered and the slide 24 is again locked to the slide 227.

In order that the slide 24 may be manually released from the slide 227, I provide a lever 271 which is secured to the rock shaft 234. A wrench 273, as shown in Fig. 9, is provided for moving the lever 271. It will be seen that the operator, by moving the lever 271, can turn the rock shaft, thus raising the cam sleeve 232 and releasing the lock. A segmental gear 272, which is pivoted to the carriage and which meshes with a rack 274 secured to the slide, is provided for moving the slide 24 forward manually. A hand lever 275 is connected with the segmental gear wheel 272. It will be seen that by lowering or raising the handle the slide 24 can be moved forward or backward as desired.

In many cases, the cutter, which has been formed by a machine constructed in accordance with my invention, is shortened or lengthened during the hardening process. In order to compensate for such variation in length of the contour on the formed cutter during the hardening process, the length of the contour formed on the cutter is varied relative to the length of the contour on the

former member. Such variation of the length of the contour of the cutter is effected by varying the position of the former member during the cutting operation.

5 A guide member 276, which is mounted on the carriage 21 adjacent to the former member 26, is provided for so operating the screw shaft 31 as to compensate for the variations in length of the contour of the 10 formed cutter which are effected during the hardening operation. The guide member 276 is rotatably adjusted about a bolt 277. A second bolt 278, which passes through a slot 279 in the guide member 276, is provided for holding the slide in any set position. The guide member 276 is provided with a guideway 280.

Two lugs 281, which extend from the side of the bracket 28, serve to slidably support 20 a bar 282. The bar 282 carries rack teeth 283 which mesh with the teeth on a gear wheel 284 mounted on the screw shaft 31. A sliding block 285 is attached to the bar 282 near the opposite end thereof. Such block 25 is pivotally connected to the bar 282 and is fitted to the guideway 280 in the guide member 276.

The guide member 276 is positioned parallel to or at an angle to the line of movement of the carriage 21 according to the desired length of contour that is to be cut on the blank. If the member 276 is set parallel to the line of movement of the carriage, the 30 contour formed on the blank will be the same length as the contour on the former member. If the member 276 is set at an angle above or below the line of movement of the carriage passing through the bolt 277, the contour cut on the blank will be lengthened or shortened as desired. In the above 40 construction, the member 276 effects movement in accordance with the movement of the carriage 21 and accordingly moves the bar 282 not only in accordance with the movement of the carriage but also in accordance with the angle the member 276 is set relative to the line of movement of the carriage. The bar 282 operates the gear wheel 284 to vary the position of the former member 50 26.

In many cases, it may be desirable to effect relieving movements of the cutting tool along lines extending not only backward and inward but also to the right or left as desired. Thus, if the finished blank is to have a side making an angle of less than five degrees, it is desirable to have the teeth of such cutter side relieved. Referring particularly to Figs. 1, 2, 21 and 22, the tool 60 slide 38 is shown carrying a side relieving slide 43. The slide 43 is adapted to effect movement perpendicularly to the line of movement of either the slide 37 or the tool slide 38. The slide 43 is fitted to a suitable 65 guideway 41 in the tool slide 38 as shown in

Fig. 22 of the drawings. A screw shaft 289 is provided for effecting movement of the slide 43 in accordance with the movement of the relieving slide 37. The shaft 289 is rotatably supported by means of plates 290 and 291 which are suitably attached to the tool slide 38. The plate 291 carries a lug 292 which extends into an orifice formed in the slide 43. One end of the shaft 289 has a bearing on the lug 292. A set screw 293, 70 which projects through the plate 291, is provided for engaging the end of the shaft 289 to prevent any longitudinal movement thereof. The shaft 289 is provided with a collar 294 which engages one side of a lug 75 extending from the plate 290. A nut 295 is mounted on the shaft and is connected to the slide 43 so as to effect movement of the slide in accordance with the rotation of the shaft. A lever 296 is mounted on a portion 80 of the shaft 289 which extends beyond the plate 290. The lever is suitably attached to the shaft by means of a bolt 297 as shown in Fig. 22 of the drawings. A bolt 298, which is mounted on the slide 24, is connected to 85 the lever 296 by means of a link 299. The link 299 is joined to the lever 296 by means of a bolt 300. The bolt 300 is fitted to a slot 301 formed in the lever 296 and the bolt 298 is fitted to a slot 302 formed in the 90 link 299. By means of such bolt and slot connections between the link 299 and the slide 24 and between the link 299 and the lever 296, the rotative movement of the shaft 289 in accordance with the relieving 95 movements may be varied. Moreover, the position of the slides may be varied. In the above construction, it is apparent the slide 43 effects a movement perpendicular to the line of movement of the slide 37 and in accordance with the movement thereof. 100

In some cases, it may be desirable to simultaneously form a number of cutter blanks in the machine or it may be desirable to have a number of tools simultaneously 110 operate on one cutter blank. A tool post carrying a number of cutting tools for simultaneously operating on one blank or on a number of blanks is illustrated in Figs. 33 to 36 inclusive of the drawings. The frame 115 303 of the tool post is preferably formed as an integral part of the slide 43. The tool post is very similar to the tool post shown in Fig. 8 of the drawings with the exception that a plurality of tools are provided. The frame 303 is provided with a top plate 304 which is attached to the frame by means of bolts 305. The cutting tools 306 are similar in construction to the cutting tool 25 heretofore described and each has the rear end thereof formed at an angle corresponding to the relief on the cutting end. A front plate 307, which is secured to the frame 303 by suitable screws 308, carries bolts 309 which engage the rear ends of the cutting 120 125 130 tools.

tools 306. The cutting tools are held in engagement with the top plate 304 by means of wedge members 310 and 311. The wedge members 311 are adjusted by bolts 312 which extend through the front plate 307. Wedge members 312 and 313, which are controlled by the bolts 314, are provided between the cutting tools in order to relatively adjust such tools.

10 In the above construction, it is apparent the tools 306 may be simultaneously controlled to cut a plurality of blanks in accordance with one former member. It is also apparent each cutting tool 306 may be 15 sharpened by grinding the top face without varying the adjustment of the bolt 309.

Referring to Figs. 1 and 23 of the drawings, projecting portions 315 on the front of the carriage 21 are shown provided with 20 rollers 316, which engage plates 317 on the slide 24. The plates 317 are preferably formed of hardened steel and are secured to the slide in any suitable manner. Such rollers are disposed at each side of the slide 25 24 near the front thereof. Rollers are also located in the casings 115 near the rear of the slide 24. Inasmuch as each of such rollers are similar in construction and operation, only one of them will be described in detail. The rollers 316 mounted near the front of the slide 24 are exactly similar in construction to the rollers 116 which are enclosed in the casings 115. The rollers 316 are each enclosed in a casing 318 and comprise an inner race member 319 and an outer race member 320. Roller members 321 are disposed in the usual manner between the race members. The outer race member 320 engages the plate 317. A bolt 322 which is secured to the casing 318 extends downwardly into the projecting portion 315 and carries a cylindrical portion 323 which is fitted to the inner race member 319. Such cylindrical portion 323 is eccentric with respect to the body portion of the bolt 322. Upon turning the bolt, the portion 323 serves to adjust the position of the roller with respect to the plate 317. A bolt 324 is provided for holding the bolt 322 in any set position. In Fig. 23 of the drawings, it should also be noted that the rollers 243 and 244, which support the slide 24 under certain conditions, are also constructed similar to the rollers which guide the slide 24.

It is apparent the above described machine is adapted for shaping a cutter blank to cut any predetermined contour while side relieving the teeth thereon. The teeth on the blank, which is so shaped, may have radially arranged or non-radially arranged cutting faces. The teeth on the cutter blanks of the type under consideration are generally relieved by a combination of the so-called radial relief and the so-called side re-

lief. The amount of side relief in all cases is very small as compared with the radial relief. In shaping a blank having undercut teeth it is always necessary to compensate the radial relieving operation in accordance 70 with the undercut on the teeth. However, it is unnecessary to effect any compensation for the side relieving movements. It is true that a theoretical error is introduced when side relief is applied to undercut teeth. 75 However, such error is smaller than can be worked to by modern tools. The radial relieving operation is compensated in the manner heretofore set forth. If the blank teeth are provided with radially arranged cutting faces, no compensation of the relieving operation is necessary.

It is believed that the general operation of the machine will be clear from the foregoing description and that a brief summary 85 will suffice.

A former member 26 is provided having the desired contour. A blank is placed in position, this blank having been previously grooved and roughed out in any usual or preferred manner. The gearing 78 is adjusted in accordance with the degree of inclination of the helical teeth on the blank and the gearing 56-57 is adjusted in accordance with the number of teeth on the blank. By means of the hand wheels 40 and 157, a tool is adjusted transversely and longitudinally into engagement with the blank at the right hand end thereof. Then the machine is started, the spindle 79 and the operating shaft 174 operating alternately in succession. During the rotative movement of the blank, relieving movements of the tool are effected as desired, thus cutting the desired relief on the teeth of the blank. Such relieving movements of the tool may follow lines extending backwardly and inwardly or may follow lines extending backwardly and inwardly and to the right or left as desired. After one complete revolution of the blank, the rotative movement of the spindle is stopped and also the relieving movements of the tool. The carriage is then fed longitudinally towards the left, the blank turning slightly in conformity with the helical teeth. Just prior to the longitudinal movement, the tool slide is withdrawn, thus withdrawing the tool from the blank and the former pin from the former member. After the longitudinal movement, the tool slide is moved slowly in the opposite direction, thus gently returning the former pin to the former member which is engaged at a new position. The tool assumes a corresponding position with respect to the blank. After this movement of the tool and the former pin, the blank is again rotated through one revolution and these movements are repeated alternately in succession until the blank is completely formed. The relieving

operation is changed in accordance with changes in diameter as already described to compensate for the non-radial cutting faces on the teeth of the blank. The guide member 5 276 is adjusted for any variation in length of the contour cut on the blank relative to the contour of the former member. The side relieving mechanism heretofore described may also be adjusted to provide any 10 desired side relief on the teeth of the blank.

Modifications in the machine and in the arrangement and location of parts may be made within the spirit and scope of my invention and such modifications are intended 15 to be covered by the appended claims.

What I claim is:

1. In a machine for operating on a cutter blank having helical teeth provided with non-radially arranged cutting faces, the 20 combination comprising means for rotating the blank, a cutting tool adapted to engage the blank, means for effecting feeding movements between the tool and the blank for shaping the latter to cut a predetermined 25 contour, means for effecting relieving movements of the tool along lines extending backwardly and inwardly from the front cutting edge of each tooth in conformity with the helical teeth on the blank while 30 compensating at different blank diameters for the non-radial cutting faces of the teeth, and auxiliary means for changing the direction of the relief lines to side relieve the teeth of the blank.
- 35 2. In a machine for operating on a cutter blank, the combination with means for rotating the blank, a cutting tool adapted to engage the blank, and a former member having a predetermined contour, of means guided by said former member for intermittently operating the cutting tool to shape the blank to cut the predetermined contour of the former member, means for additionally operating the cutting tool to relieve the blank teeth along lines extending 40 backwardly and inwardly from the front cutting edge of each tooth and in conformity with the blank rotation, and auxiliary means for so moving the cutting tool as to change 45 the direction of the relief lines to side relieve the teeth of the blank.
- 50 3. In a machine for operating on a cutter blank having helical teeth, the combination with means for rotating the blank, a cutting tool adapted to engage the blank, and a former member having a predetermined contour, of means guided by said former member for operating the cutting tool to shape the blank to cut the predetermined contour 55 of the former member, means for operating the cutting tool to relieve the blank teeth along lines extending backwardly and inwardly from the front cutting edge of each tooth and in conformity with the helical teeth and the non-radial cutting faces, and means for varying the length of the contour formed on the blank relative to the length of the contour on the former member.
- 60 4. In a machine for operating on a cutter blank having helical teeth provided with non-radially arranged cutting faces, the combination with means for rotating the blank, a cutting tool adapted to engage the blank, and a former member having a pre- 65

the cutting tool as to change the direction of the relief lines to side relieve the teeth of the blank.

4. In a machine for operating on a cutter blank having helical teeth provided with 70 non-radially arranged cutting faces, the combination with means for rotating the blank, a cutting tool adapted to engage the blank, and a former member having a predetermined contour, of means guided by 75 said former member for so operating the cutting tool as to shape the blank to cut the predetermined contour of the former member, means for additionally operating the cutting tool to relieve the blank teeth 80 along lines extending backwardly and inwardly from the front cutting edge of each tooth and in conformity with the blank rotation while compensating at different blank diameters for the non-radial cutting 85 faces on the teeth of the blank, and auxiliary means for so moving the cutting tool as to change the direction of the relief lines to side relieve the teeth of the blank.

5. In a machine for operating on a cutter blank, the combination comprising a cutting tool adapted to engage the cutter blank, a former member having a predetermined non-rectilinear contour, means controlled by said former member for effecting feeding 90 movements between the tool and the blank to shape the blank to cut the contour of the former member, means for operating the tool to relieve the teeth of the blank along 95 lines extending backwardly, inwardly and to the right or to the left from the front cutting edge of each tooth, and means for varying the length of the contour formed on the blank relative to the length of the contour on the former member.

6. In a machine for operating on a cutter blank having helical teeth provided with non-radially arranged cutting faces, the combination with a cutting tool adapted to engage the blank, a former member having a predetermined contour, means controlled by the former member for effecting feeding movements between the tool and the blank to shape the blank to cut the contour of the former member, means for operating the tool to relieve the teeth of the blank along 100 lines extending backwardly, inwardly and to the right or left from the front cutting edge of each tooth, such relief being effected in conformity to the helical teeth and the non-radial cutting faces, and means for varying the length of the contour formed on the blank relative to the length of the contour on the former member.

7. In a machine for operating on a cutter blank having helical teeth provided with non-radially arranged cutting faces, the combination with means for rotating the blank, a cutting tool adapted to engage the blank, and a former member having a pre- 105

110

- determined non-rectilinear contour, of means controlled by the former member for effecting intermittent feeding movements of the tool to shape the blank to cut the predetermined contour of the former member, and means for operating the cutting tool in timed relation to the blank rotation to relieve the blank teeth along lines extending backwardly, inwardly, and to the right or to the left from the front cutting edge of each tooth, such relief lines being effected in conformity with the helical teeth and the non-radial cutting faces.
8. In a machine for operating on a cutter blank, the combination comprising a rotatable blank-carrying spindle, a cutting tool, mechanism for effecting relative feeding movement between the tool and the blank longitudinally of the latter, mechanism acting independently of the feeding mechanism for effecting relieving movements of the tool at a normally uniform frequency and along lines extending backwardly, inwardly and to the right or to the left from the front cutting edge of each tooth, and mechanism for varying the spindle rotation relatively to the uniform relieving movements to effect relieving in conformity with helical teeth on the blank inclined in either direction.
9. In a machine for operating on a cutter blank, the combination comprising a rotatable blank-carrying spindle, a cutting tool, automatic means for effecting intermittent feeding movements of the tool with respect to the blank, and automatically acting mechanism for effecting relieving movements along lines extending backwardly, inwardly, and to the right or to the left from the front cutting edge of each tooth.
10. In a machine for operating on a cutter blank, the combination comprising a rotatable blank-carrying spindle, a cutting tool, automatic means for effecting regular step-by-step feeding movements of the tool with respect to the blank, automatic mechanism for moving the tool inward or outward as longitudinal movement takes place to cut the blank with a predetermined contour, and automatically acting mechanism for effecting regular relieving movements of the tool independent of the aforesaid movements and along lines extending backwardly, inwardly and to the right or to the left from the front cutting edge of each tooth.
11. In a machine for operating on a cutter blank, the combination comprising a rotatable blank-carrying spindle, a cutting tool, a former member having a predetermined contour, automatic means for effecting regular step-by-step feeding movements of the tool with respect to the blank, automatic mechanism controlled by said former member for moving the tool inward or out-

ward as longitudinal movement takes place to cut the blank in accordance with the contour of the former member, automatically acting mechanism for effecting regular relieving movements of the tool independent of the aforesaid movements and along lines extending backwardly, inwardly, and to the right or to the left from the front cutting edge of each tooth, and means for varying the length of the contour formed on the blank relative to the length of the contour on the former member.

12. In a machine for operating on a cutter blank, the combination comprising a rotatable blank-carrying spindle, a cutting tool, automatic means for effecting intermittent longitudinal feeding movements between the tool and the blank, means for moving the tool inward or outward as longitudinal movement takes place to cut the blank with different diameters, automatically acting mechanism for effecting regular supplemental relieving movements of the tool independent of the aforesaid movements and along lines extending backwardly, inwardly and to the right or to the left from the front cutting edge of each tooth, and automatic means for stopping the spindle rotation and the relieving movements at the time of each feeding movement.

13. In a machine for operating on a cutter blank, the combination comprising a rotatable spindle carrying a blank having generally longitudinal grooves therein, a cutting tool, automatic means for withdrawing the tool from the blank at intervals, automatically acting mechanism for effecting regular relieving movements of the tool supplemental to said withdrawing movements between each two withdrawing movements, the relieving movements following lines extending backwardly, inwardly and to the right or left from the front cutting edge of each tooth, and automatic means for stopping the spindle rotation and the relieving movements at the time of each withdrawing movement.

14. In a machine for operating on a cutter blank having helical teeth provided with non-radially arranged cutting faces, the combination comprising a cutting tool, means for effecting feeding movements between said tool and the blank, means for effecting relieving movements of the tool along lines extending backwardly, inwardly and to the right or left from the front cutting edge of each tooth, and means to compensate the relieving operation at different blank diameters for the non-radial cutting faces of the teeth.

15. In a machine for operating on a cutter blank having teeth provided with non-radially arranged cutting faces, a cutting tool, mechanism for effecting relieving movements of the tool at a normally uniform fre-

- quency along lines extending backwardly, inwardly and to the right or to the left from the front cutting edge of each tooth, and means to compensate the relieving operation 5 at different blank diameters for the non-radial cutting faces on the teeth of the blank.
16. In a machine tool, the combination with a rotatable spindle adapted to carry a blank having helical teeth, a cutting tool 10 adapted to engage the blank, a slide movable longitudinally with respect to the blank axis for carrying said tool, and a second slide movable transversely with respect to the blank axis and adapted to support said first 15 slide, of means for simultaneously moving said slides at normally uniform frequency to effect relieving movements of the tool along lines extending backwardly, inwardly and to the right or to the left from the front cutting face of each tooth and in conformity 20 with the helical teeth on the blank.
17. In a machine tool, the combination with a rotatable spindle adapted to carry a blank having helical teeth, a cutting tool 25 adapted to engage the blank, a slide carrying said tool and moved longitudinally along the blank, a second transversely movable slide carrying said longitudinally movable slide, and a third slide movable transversely 30 with respect to the blank and carrying said second slide, of means for operating said second slide with respect to the third slide to effect relieving movements of the tool in conformity with the helical teeth on the 35 blank, and means for effecting relieving movements of the first mentioned slide in conformity with the movements of the second slide.
18. In a machine tool, the combination 40 with a rotatable blank-carrying spindle, a cutting tool adapted to engage the blank, a slide movable longitudinally with respect to the blank axis for carrying said tool, and a second slide movable transversely with respect to the blank axis and adapted to support said first slide, of means for effecting regular relieving movements of said second slide, and means comprising a screw shaft mounted on said second slide and threadably connected to the first slide for effecting independent movement of the first slide in conformity to the relieving movements of the second slide.
19. In a machine tool, the combination 45 with a rotatable blank-carrying spindle, a cutting tool adapted to engage the blank, a slide movable longitudinally with respect to the blank axis for carrying said tool, a second slide movable transversely with respect 50 to the blank axis and adapted to support said first slide, and means for supporting the second slide, of means for effecting regular relieving movements of said second slide, a screw shaft mounted on said second slide and threadably connected to the first slide and connected to the supporting means for the second slide to effect independent relieving movements of the first slide in conformity with the relieving movements of the second slide.
20. In a machine tool, the combination 55 with a rotatable spindle adapted to carry a blank having helical teeth, a cutting tool adapted to engage the blank, a slide carrying said tool and movable with respect to the blank, a second slide carrying first slide and adapted to move at an angle with respect to the line of movement of the first slide, and means for supporting said second slide, of means for effecting regular relieving movements of said second slide in conformity with the helical teeth on the blank, and connecting means between the two slides and said support for effecting independent relieving movements of the first slide in conformity to the relieving movements of the second slide.
21. In a machine tool, the combination 60 with a rotatable blank-carrying spindle, a cutting tool adapted to engage the blank, a slide carrying said tool and movable with respect to the blank, a second slide carrying said first slide and adapted to move at an angle with respect to the line of movement of the first slide, and means for supporting said second slide, of means for effecting regular relieving movements of said second slide, a screw shaft mounted on the second slide and threadably connected to the first slide, and a lever arm on said shaft connected to the supporting means for the second slide to effect independent relieving movements of the first slide in conformity with the relieving movements of the second slide.
22. In a machine tool, the combination 65 with a rotatable spindle adapted to carry a blank having helical teeth, a cutting tool adapted to engage the blank, a slide carrying said tool and movable with respect to the blank, a second slide carrying said first slide and adapted to move at an angle with respect to the line of movement of the first slide, and means for supporting said second slide, of means for effecting regular relieving movements of said second slide in conformity with the helical teeth on the blank, connecting means between the two slides and said support for effecting independent relieving movements of the first slide in conformity to the relieving movements of the second slide.
23. In a machine for operating on a cutter blank having helical teeth, the combination 70 with a cutting tool adapted to engage the blank, means for rotating the blank, and a former member having a predetermined non-rectilinear contour, of means guided by

the former member for effecting intermittent movement between the tool and the blank to shape the blank so as to cut the predetermined contour, means for effecting relieving movements between the tool and the blank in conformity to the helical teeth, a guide member, and auxiliary means operated in accordance with the position of the guide member for varying the former member to vary the length of the contour cut on the blank.

24. In a machine for operating on a cutter blank having helical teeth, the combination comprising means for rotating the cutter blank, a cutting tool, a former member having a predetermined contour, means guided by said former member for intermittently operating the cutting tool for shaping the teeth of the blank to cut the predetermined contour while relieving the teeth of the blank, and means comprising an adjustable guide member for varying the length of the contour formed on the blank relative to the length of the contour on the former member to compensate for the variations in length of the blank effected during hardening.

25. In a machine for operating on a cutter blank having helical teeth provided with non-radially arranged cutting faces, the combination comprising means for rotating the blank, a cutting tool for engaging the blank, a former member having a predetermined contour, means for so guiding the cutting tool by said former member as to shape the blank to cut the predetermined contour, and adjustable guide member, and means for varying the position of the said guide member to change the length of the contour formed on the blank relative to the length of the contour on the former member.

26. In a machine for operating on a cutter blank having helical teeth provided with non-radially arranged cutting faces, the combination with means for rotating the blank, a cutting tool for engaging the blank, and a former member having a predetermined contour, of means controlled by said former member for effecting relative movement between the blank and the cutting tool for shaping the blank to cut a contour corresponding to the contour of the former member while relieving the blank teeth in conformity to the inclination of teeth relative to the blank axis and compensating the relieving operation for the non-radially arranged cutting faces of the teeth, a guide member, and means for varying the position of the guide member to change the length of the contour formed on the blank.

27. In a machine for operating on a cutter blank, the combination comprising means for rotating the cutter blank, a cutting tool, a former member having a predetermined contour, means controlled by the

former member for operating the cutting tool for shaping the blank to cut the predetermined contour, and auxiliary means comprising an inclined slide for operating the former member to vary the length of the contour on the blank to compensate for the change in length of the blank which is effected during hardening.

28. In a machine for operating on a cutter blank having helical teeth, the combination comprising a cutting tool adapted to engage the blank, a former member, means guided by said former member for effecting intermittent feeding movements between the tool and the blank to cut the blank to different diameters, means for effecting relieving movements between the tool and the blank in conformity with the helical teeth on the blank, and means comprising an inclined slide for varying the length of the contour formed on the blank to compensate for the variations in length effected during hardening.

29. In a machine for operating on a cutter blank, the combination with a cutting tool adapted to engage the blank, means for rotating the blank, and a former member having a predetermined contour, of means guided by the former member for effecting intermittent feeding movements of the tool with respect to the blank to shape the blank to cut the blank to the predetermined contour of the former member, means for effecting relieving movements of the tool in timed relation to the blank rotation, and means comprising an inclined slide for varying the position of the former member relative to the blank in accordance with the movement of the tool along the blank to vary the length of the contour formed on the blank.

30. In a machine for operating on a cutter blank having helical teeth provided with non-radially arranged cutting faces, the combination comprising a cutting tool, means for effecting feeding movements between said tool and the blank to form a cutter adapted to cut a predetermined contour, means for effecting relieving movements between the tool and the blank in conformity with the helical teeth on the blank and for compensating at different blank diameters for the non-radial cutting faces on the teeth of the blank, a guide member, and means for varying the position of the guide member to automatically vary the length of the contour formed on the blank.

31. In a machine for operating on a cutter blank having helical teeth, the combination comprising a cutting tool, means for effecting feeding movements between said tool and the blank to form a cutter adapted to cut a predetermined contour, means for effecting relieving movements between the tool and the blank in conformity with the helical teeth on the blank, and means for

automatically increasing or decreasing the length of the contour formed on the blank in accordance with the feeding movements to compensate for the variations in length 5 of the blank effected during hardening.

32. In a machine for operating on a cutter blank, the combination with a cutting tool adapted to engage the blank, means for rotating the blank, and a former member 10 having a predetermined contour, of means guided by the former member for moving the cutting tool along the blank to shape the blank to cut the predetermined contour, means for effecting relieving movements of 15 the tool in timed relation to the blank rotation, and means comprising an inclined slide for varying the position of the former member relative to the blank in accordance with the movement of the tool along the blank to 20 vary the length of the contour formed on the blank.

33. In a machine for operating on a cutter blank having helical teeth, the combination with a cutting tool adapted to engage the blank, means for rotating the blank, and a former member having a predetermined contour, of means guided by the former member for effecting feeding movements of the tool with respect to the blank to shape the blank 25 30 to cut the contour of the former member, means for effecting relieving movements of the tool in conformity with the helical teeth on the blank, and means comprising an inclined slide for varying the position of the former member relative to the blank in accordance with the movement of the tool along the blank to vary the length of the contour formed on the blank.

34. In a machine for operating on a cutter 40 blank, the combination comprising means for rotating the blank, a cutting tool, a former member having a predetermined contour, means for effecting feeding movements of the tool longitudinally of the blank, automatic mechanism controlled by said former member for moving the tool inward or outward as longitudinal movement takes place 45 to cut the blank in accordance with the contour of the former member, automatically 50 acting mechanism for effecting regular relieving movement of the tool independent of the aforesaid movements, and means comprising a guide member for increasing or decreasing the length of the contour formed 55 on the blank relative to the length of the contour on the former member.

35. In a machine tool, the combination comprising a rotatable spindle adapted to carry a plurality of blanks, a plurality of 60 cutting tools respectively adapted to engage the blanks carried by said spindle, a former member having a predetermined contour, means so controlled by said former member as to operate each cutting tool for shaping 65 the associated blank to cut the contour of

the former member, and means for operating all of said tools to effect relieving movements along lines extending backwardly, inwardly and to the right or to the left from the front cutting edge of each tooth and in 70 conformity with helical teeth on the blanks.

36. In a machine tool, the combination comprising a rotatable spindle adapted to carry a plurality of blanks each having helical teeth provided with non-radially arranged cutting faces, a plurality of cutting tools respectively adapted to engage the blanks carried by the spindle, a former member having a predetermined contour, means so controlled by said former member 75 as to operate each cutting tool for shaping the associated blank to cut the contour of the former member, and means for operating all of said tools to effect relieving movements along lines extending backwardly, inwardly and to the right or to the left from the front cutting edge of each tooth and in 80 conformity with the helical teeth on the blanks while compensating for the non-radial cutting faces on the teeth. 85

37. In a machine tool, the combination comprising a rotatable work-carrying spindle, a plurality of cutting tools adapted to engage the work, means for operating all of 90 said tools to cut the work in accordance with a predetermined contour, and means for operating all of said tools to effect relieving movements along lines extending backwardly, inwardly and to the right or to the left from the front cutting edge of each tooth and in 95 conformity with the helical teeth on the work. 100

38. In a machine tool, the combination comprising a rotatable spindle adapted to carry a plurality of blanks, a plurality of cutting tools respectively adapted to engage the blanks carried by said spindle, a former member having a predetermined contour, means so controlled by said former member 105 as to operate each cutting tool to shape the associated blank to cut the contour of the former member, means for operating all of said tools to effect relieving movements in conformity with helical teeth on the blank, and means for varying the length of the contour formed on each blank relative to the contour on the former member. 110

39. In a machine tool, the combination comprising a rotatable spindle adapted to carry a plurality of blanks each having helical teeth provided with non-radially arranged cutting faces, a plurality of cutting tools respectively adapted to engage the blanks carried by the spindle, a former member having a predetermined contour, means so controlled by said former member 120 as to operate each cutting tool for forming the associated blank to cut the contour of the former member, means for operating all of said tools to effect relieving movements 125 130

in conformity with the helical teeth on the blank while compensating for the non-radial cutting faces on the teeth, and means for varying the length of the contour on each blank relative to the length of the contour of the former member.

40. In a machine tool, the combination comprising a rotatable work-carrying spindle, a plurality of tools adapted to engage the work, means for operating all of said tools to cut the work in accordance with a predetermined contour, means for adjusting the tools transversely and longitudinally with respect to each other, and means for adjusting the tools jointly with respect to the work.

41. In a machine tool, the combination comprising a rotatable work-carrying spindle, a plurality of cutting tools adapted to engage the work, means for operating all of said tools to cut the work in accordance with a predetermined contour, means for independently adjusting the cutting tools with respect to the work, means for adjusting the tools jointly with respect to the work, and means for effecting relieving movements of all the cutting tools with respect to the work.

42. In a machine tool, the combination comprising a rotatable blank-carrying spindle, drive mechanism for the spindle, a cutting tool, mechanism for effecting relative feeding movements between the tool and the blank longitudinally of the latter, mechanism including a relatively movable rack and pinion interposed between the drive mechanism and the spindle for varying the rotation of the latter, and means for disconnecting said rack from the spindle to permit the resetting of the rack without changing the rotative position of the spindle or the position of the cutting tool.

43. In a machine tool, the combination comprising a rotatable blank-carrying spindle, drive mechanism for the spindle, a cutting tool, mechanism for effecting relative feeding movement between the tool and the blank longitudinally of the latter, mechanism including bodily rotatable gearing interposed between the drive mechanism and the spindle for varying the rotation of the latter, and means for disconnecting said bodily rotatable gearing from the spindle to reset it without changing the rotative position of the spindle or the position of the cutting tool so that a blank of extreme length may be operated on.

44. In a machine tool, the combination comprising a rotatable blank-carrying spindle, drive mechanism for the spindle, a cutting tool, mechanism for effecting relative feeding movement between the tool and the blank longitudinally of the latter, mechanism including a rack and bodily rotatable gearing interposed between the drive

mechanism and the spindle for varying the rotation of the latter, and means for disconnecting said mechanism including said rack from the spindle to reset it without changing the rotative position of the spindle or the position of the cutting tool so that a blank of extreme length may be operated on.

45. In a machine tool, the combination comprising a rotatable blank-carrying spindle, drive mechanism for the spindle, a cutting tool, means for feeding the tool longitudinally of the spindle and blank, mechanism supplemental to the drive mechanism and including a rack for varying the spindle rotation without interrupting the power connection between the drive mechanism and the spindle, and means for disconnecting said rack to reset it when moved to an extreme position.

46. In a machine tool, the combination comprising a rotatable blank-carrying spindle, driving mechanism for the spindle, a cutting tool, mechanism for effecting relative feeding movements between the tool and the blank longitudinally of the latter, mechanism interposed between the spindle and the drive mechanism and supplemental to the latter for varying the spindle rotation, the said mechanism comprising a shaft, two relatively rotatable sleeves mounted on the shaft, a rack carried by the shaft, gearing meshing with the rack and connecting the two sleeves, and means for effecting relative movement between the rack and the gearing to turn one sleeve relative to the other, and means for disconnecting said rack to reset it when moved to an extreme position.

47. In a machine tool, the combination comprising a blank-carrying spindle, a cutting tool movable transversely of the spindle axis toward or from the blank, means for moving the tool toward the blank, and means for retarding the said movement of the tool including a cylinder and a piston therein, the said cylinder having a valved aperture aligned with said piston for permitting the rapid flow of fluid when the tool is moved away from the blank and for restricting the flow of fluid when the tool is moved toward the blank.

48. In a machine tool, the combination comprising a blank-carrying spindle, a cutting tool movable transversely of the spindle axis toward or from the blank, means for moving the tool toward the blank, means for retarding the said movement of the tool including a cylinder and a piston therein, the said cylinder having a valve in it for permitting the free flow of liquid therethrough when the tool is moved away from the blank and for restricting the flow of liquid when the tool is moved toward the blank.

49. In a machine tool, the combination comprising a blank-carrying spindle, a cutting tool movable transversely of the spindle axis toward or from the blank, means to permit transverse movement, and means comprising cam bars for elevating the slide out of contact with the support when it is released.
- 5 for moving the tool toward the blank, means for retarding the said movement of the tool including a cylinder and a piston therein, the said cylinder having a valve in it for permitting the free flow of liquid there- 70
- 10 through when the tool is moved away from the blank and for restricting the flow of liquid when the tool is moved toward the blank, and a rod aligned with said cylinder for adjusting the position of said valve.
- 15 50. In a machine tool, the combination comprising a blank-carrying spindle, a cutting tool movable transversely of the spindle toward or from the blank, means for moving the tool toward the blank, means for retarding the said movement of the tool including a cylinder and a piston therein, a fluid reservoir associated with the cylinder, the said cylinder having a single valve for permitting the free flow of liquid between the cylinder and the reservoir when the tool is moved away from the blank and for re- 75
- 20 stricting the flow of liquid between the cylinder and the reservoir when the tool is moved toward the blank.
- 25 51. In a machine tool, the combination comprising a blank-carrying spindle, a cutting tool movable transversely of the spindle toward or from the blank, means for moving the tool toward the blank, means for re- 80
- 30 stricting the said movement of the tool including two cylinders each having a piston therein, a fluid reservoir associated with said cylinders, each of said cylinders having one valve associated with it for permitting the free flow of liquid between the associated cylinder and the reservoir when the tool is moved away from the blank and for restrict- 85
- 35 ing the flow of liquid between the associated cylinder and the reservoir when the tool is moved toward the blank.
- 40 52. In a machine tool, the combination comprising a blank-carrying spindle, a cutting tool movable transversely of the spindle toward or from the blank, a piston rod con- 90
- 45 nected to the tool, a spring surrounding said rod and serving to move the tool toward the blank, and means for retarding the movement of the tool toward the blank including a cylinder and a piston therein, the piston being connected to said rod, the said cylinder having a valve in it for permitting the free flow of liquid therethrough when the tool is being moved away from the blank and for restricting the flow of liquid when the tool is being moved toward the blank. 95
- 50 53. In a machine tool, the combination comprising a rotatable blank-carrying spindle, a transversely movable tool slide, a support for the tool slide, means for locking the slide to the support or for releasing it to permit transverse movement, and means comprising anti-friction rollers and cam bars for operating the rollers to elevate the slide out of contact with the support when it is released. 100
- 55 54. In a machine tool, the combination comprising a rotatable blank-carrying spindle, a transversely movable tool slide, a support for the tool slide, automatic means for locking the slide to the support at intervals and for releasing it at intervals to permit transverse movement, and automatic means comprising rollers operated by cam bars for elevating the slide out of contact with the support each time it is released. 105
- 60 55. In a machine tool, the combination comprising a rotatable blank-carrying spindle, a transversely movable tool slide, a support for the tool slide, automatic means for locking the slide to the support at intervals and for releasing it at intervals to permit transverse movement, and automatic means comprising rollers operated by cam bars for elevating the slide out of contact with the support each time it is released. 110
- 65 56. The method of shaping a cutter blank having helical teeth, which consists in rotating the blank, in providing a cutting tool in operative relation to the blank, in effecting feeding movements between the tool and the blank to cut the blank to different diameters, and in effecting relieving movements of the tool in conformity with the helical teeth on the blank and along lines extending backward, inward, and to the right or left from the front cutting edge of each tooth. 115
- 70 57. The method of shaping a cutter blank having teeth provided with non-radially arranged cutting faces, which consists in rotating the blank, in providing a cutting tool in operative relation to the blank, in effecting feeding movements between the tool and the blank to cut the blank to different diameters, in effecting relieving movements of the tool in conformity with the blank rotation and along lines extending backward, inward, and to the right or left from the front cutting edge of each tooth, and in compensating the relieving operation at different blank diameters for the non-radial cutting faces on the teeth. 120
- 75 58. The method of shaping a cutter blank having helical teeth provided with non-radially arranged cutting faces, which consists in rotating the blank, in providing a cutting tool in operative relation to the blank, in effecting feeding movements between the tool and the blank to cut the blank to different diameters, in effecting relieving movements of the tool in conformity with the helical teeth on the blank and along lines extending backward, inward, and to the right or left from the front cutting edge of each tooth, and in compensating the relieving operation at different blank diameters for the non-radial cutting faces on the teeth. 125
- 80 59. The method of shaping a cutter blank 130

having helical teeth provided with non-radially arranged cutting faces, which consists in rotating the blank, in providing a cutting tool in operative relation to the blank, in providing a former member having a predetermined contour, in moving the tool in accordance with the contour of the former member for shaping the blank to cut the predetermined contour of the former member, in effecting relieving movements of the tool in conformity with the helical teeth on the blank and along lines extending backward, inward and to the right or left from the front cutting edge of each tooth, and in compensating the relieving operation at different blank diameters for the non-radial cutting faces on the teeth.

60. The method of shaping a cutter blank having teeth provided with non-radially arranged cutting faces, which consists in rotating the blank, in providing a former member having a predetermined contour, in moving the tool in accordance with the contour of the former member for shaping the blank to cut the predetermined contour of the former member, in effecting relieving movements of the tool in conformity with the blank rotation and along lines extending backward, inward and to the right or left from the front cutting edge of each tooth, in compensating the relieving operation at different blank diameters for the non-radial cutting faces on the teeth, and in varying the position of the former member during the tool movement for varying the length of the contour formed on the blank relative to the length of the contour on the former member.

61. The method of shaping a plurality of cutter blanks having helical teeth, which consists in rotating the blanks, in providing a plurality of cutting tools in operative relation to the blanks, in providing a former member having a predetermined contour, in effecting relative movements between the tools and the blanks in accordance with the contour of the former member, and in effecting relieving movements of each tool in conformity with the helical teeth on the associated blank and along lines extending backward, inward and to the right or left from the front cutting edge of each tooth.

62. The method of shaping a cutter blank having helical teeth, which consists in rotating the blank, in providing a cutting tool in operative relation to the blank, in varying the blank rotation in accordance with the helical teeth on the blank, in effecting feeding movements between the tool and the blank to cut the blank to different diameters, and in operating the tool to effect radial and axial relief on the teeth of the blank.

63. The method of shaping a cutter blank, which consists in providing a cutting tool

in operative relation to the blank, in rotating the blank, in providing a former member having a predetermined contour, in effecting relative movements between the tool and the blank under the control of the former member for shaping the blank to cut the contour of the former member, in operating the tool to effect radial and axial relief on the teeth of the blank, and in varying the length of the contour formed on the blank relative to the length of the contour on the former member.

64. The method of shaping a cutter blank having helical teeth, which consists in providing a cutting tool in operative relation to the blank, in rotating the blank, in providing a former member having a predetermined contour, in effecting relative movements between the tool and the blank under the control of the former member and in conformity with the helical teeth for shaping the blank to cut the contour of the former member, in operating the tool to effect radial and axial relief on the teeth of the blank, and in varying the length of the contour formed on the blank relative to the length of the contour on the former member.

65. The method of shaping a cutter blank, which consists in providing a cutting tool in operative relation to the blank, in intermittently feeding the tool longitudinally of the blank, in withdrawing the tool from the blank prior to each feeding movement, in restoring the tool to operative relation with the blank after each feeding movement, and in operating the tool to axially and radially relieve the teeth of the blank.

66. The method of shaping a plurality of cutter blanks, which consists in providing a cutting tool in operative relation to each blank, in intermittently feeding each tool longitudinally of the associated blank, in withdrawing the tools from the blanks prior to each feeding movement, in restoring the tools to operative relation with the blanks after each feeding movement, and in operating each tool to axially and radially relieve the teeth of the associated blank.

67. The method of shaping a cutter blank, which consists in providing a cutting tool in operative relation to the blank, in rotating the blank, in providing a former member having a predetermined contour, in effecting intermittent relative movement between the tool and the blank for shaping the latter to cut the contour of the former member, and in varying the length of the contour formed on the blank relative to the length of the contour on the former member.

68. The method of shaping a cutter blank having helical teeth, which consists in providing a cutting tool in operative relation to the blank, in rotating the blank, in providing a former member having a predeter-

5 mined contour, in effecting relative movements between the tool and the blank under the control of the former member and in conformity with the helical teeth on the blank for shaping the blank to cut the contour of the former member, and in varying the length of the contour formed on the blank relative to the length of the contour on the former member.

10 69. The method of shaping a cutter blank having helical teeth provided with non-radially arranged cutting faces, which consists in providing a cutting tool in operative relation to the blank, in rotating the blank, 70 in providing a former member having a predetermined contour, in effecting relative movements between the tool and the blank under the control of the former member and in conformity with the helical teeth on the blank for shaping the blank to cut the contour of the former member, in varying the length of the contour formed on the blank relative to the length of the contour on the former member, and in varying the relieving operation at different blank diameters to compensate for the non-radial cutting faces.

70. The method of shaping a cutter blank having helical teeth, which consists in rotating the blank, in providing a cutting tool in operative relation to the blank, in providing a former member having a predetermined contour, in effecting intermittent relative movement between the tool and the blank for shaping the latter to cut the contour of the former member, and in varying the position of the former member for varying the length of the contour formed on the blank relative to the length of the contour on the former member.

71. The method of shaping a plurality of cutter blanks having helical teeth, which consists in rotating the blanks, in providing a plurality of cutting tools in operative relation to the blanks, in providing a former member having a predetermined contour, in effecting relative movements between the tools and the blanks for shaping each of the latter to cut the contour of the former member, and in varying the position of the former member for varying the length of the contour formed on each blank relative to the length of the contour on the former member.

72. The method of shaping a plurality of cutter blanks having helical teeth provided with non-radially arranged cutting faces which consists in providing a plurality of cutting tools in operative relation to the blanks, in rotating the blanks, in providing a former member having a predetermined contour, in effecting relative movement between each tool and the associated blank under the control of the former member for shaping each blank to cut the contour of the former member, in effecting relieving movements of the tools in conformity with the teeth on the blanks.

75 tour of the former member, in varying the length of the contour formed on each blank relative to the length of the contour on the former member, in relieving the teeth on each blank, and in varying the relieving operation at different blank diameters to compensate for the non-radial cutting faces on the teeth

75 73. The shaping of a cutter blank, which consists in providing a cutting tool in operative relation to the blank, in intermittently feeding the tool longitudinally of the blank, in withdrawing the tool from the blank prior to each feeding movement, in restoring the tool to operative relation with the blank after each feeding movement, in providing a former member having a predetermined contour, in limiting the restoring movement according to the contour of the former member, and in varying the length 80 of the contour formed on the blank relative to the length of the contour on the former member.

80 74. The method of shaping a cutter blank, which consists in rotating the blank, in providing a cutting tool in operative relation to the blank, in providing a former member having a predetermined contour, in effecting intermittent longitudinal feeding movements of the tool along the blank, in effecting transverse movements of the tool with respect to the blank under the control of the former member and between the feeding movements for shaping the blank to cut the predetermined contour, in relieving the 95 teeth on the blank, and in varying the length of the contour formed on the blank relative to the length of the contour on the former member.

95 75. The method of shaping a plurality of cutter blanks having helical teeth, which consists in rotating the blanks, in providing a plurality of cutting tools in operative relation to the blanks, in providing a former member having a predetermined contour, in effecting relative movement between each cutting tool and the associated blank under the control of the former member for shaping each blank to cut the contour of the former member, and in effecting relieving movements of the tools in conformity with the teeth on the blanks.

105 76. The method of shaping a plurality of cutter blanks having helical teeth provided with non-radially arranged cutting faces, which consists in rotating the blanks, in providing a plurality of cutting tools in operative relation to the blanks, in providing a former member having a predetermined contour, in effecting relative movement between each cutting tool and the associated blank under the control of the former member for shaping each blank to cut the contour of the former member, in effecting relieving movements of the tools in conformity with the teeth on the blanks.

ity with the helical teeth on the blank, and in varying the relieving operation at different blank diameters to compensate for the non-radial cutting faces on the teeth.

- 5 77. The method of shaping a plurality of cutter blanks having helical teeth, which consists in simultaneously rotating the blanks, in providing a cutting tool in operative relation to each of said blanks, in simultaneously varying the rotation of the

blanks in accordance with the helical teeth on the blanks, in effecting relative movement between each blank and the associated tool to cut each of the blanks to different diameters, and in operating each tool to relieve the teeth on the associated blank. 15

In testimony whereof, I hereto affix my signature.

FRIEDERICH MÜLLER.
